BOXMAKING MACHINE

Vincent D. Hery, Norwood, and Beldon L. Rich,
 Cincinnati, Ohio, assignors to The American
 Tool Works, Cincinnati, Ohio, a corporation of
 Ohio

Application February 7, 1947, Serial No. 727,220

61 Claims. (Cl. 93—36.4)

1

This invention relates to the art of manufacturing containers and is particularly directed to apparatus for manufacturing boxes of rectangular shape, that is of the type having a bottom and four side walls. More particularly, the invention is concerned with the manufacture of boxes from a thermo-plastic sheet.

In the form of machine concerned in this invention, the plastic sheet is fed from a continuous roll and blanks are severed from the roll. These blanks are fed progressively through the machine for a series of operations thereon, the ultimate product being a four-sided box, the sides of which are firmly united together. In passing through the machine of this invention, the blank is subjected to a trimming operation and successive wall forming operations at which the material is crimped or formed under heat and pressure to define a bottom and four sides. The sides are bent into substantially perpendicular positions with respect to the bottom, after which they are brought together and adhesively joined or merged at the corners. Each cycle or complete rotation of the main drive shaft will produce a box, there being a plurality of boxes progressing through the stations of the machine at any given time. The boxes are moved from station to station by means of conveyor mechanism, the drive for which is synchronized with the mechanisms operating at the stations.

One of the problems arising in the manufacture of boxes from plastic material, or materials of the type which are transparent, is to maintain the transparency and finish of the material through the art of producing the box without marring the surface of the material, that is without scratching, indenting or damaging the material in any way. The present inventor accomplishes the result of forming boxes from a continuous strip of plastic material without in any way damaging the surface of the material. The mechanisms employed in the machine operate on the material throughout the various stages of production without subjecting it to a rubbing contact with the metal parts of the machine and perform all bending or crimping operations without deformation of the material other than the crimping or bending necessary to the formation of the box.

The present machine has been designed to fulfill the following general objectives: first, it operates on the plastic sheet in such manner that its finish is not marred nor is its transparency, if transparent, reduced by rubbing on the parts of the machine and therefore the ap-

2

pearance of the material is maintained; second, the parts of the box produced are firmly sealed together; third, the boxes are uniform in shape; fourth, the machine is capable of the production of boxes in large quantity, that is to say it can be operated rapidly, producing one thousand to fifteen hundred boxes per hour; fifth, it is positive in operation requiring very little attendance; sixth, it is adjustable to produce rectangular or square boxes of various sizes ranging from approximately two and one-half inches in width or length to thirteen inches in width or length and approximately three-eights of an inch high to four inches high; and seventh, the various mechanisms may be accurately adjusted so as to align the feed of the material from the roll to and through the various stations.

A further more detailed object has been accomplished in the production of a machine of the character above defined in which the plastic sheet, as fed from the reel, is in roll form, and in which an intermittent feed device is employed which will deliver successive sections of the roll of material to the cut-off knives which sever these sections from the roll in a highly accurate manner. The material is fed an amount equal to its width, whereupon the blank as cut from the roll is square. The severed end sections or blanks are successively delivered to carrier elements and attached thereto for movement through the various work stations.

A still further more detailed object is to provide for accurate alignment of the feed reel relative to the mechanisms which feed the blanks through the machine and to provide a feeding mechanism with operating devices which will not permit back-lash of the roll strip when the feed pauses to permit severance.

A still further more detailed object has been 40 to provide for accurate alignment of the reel with the mechanisms at the several stations and the blank transporting means so that the blanks are initially delivered into positions where they are gripped by the successive carriers for 45 accurately aligned feed through the machine.

A still further object has been to provide an 50 endless conveyor mechanism having a series of carriers thereon, which carriers are spaced on the mechanism the exact distance between stations and which carriers include suction means adapted to grip the blanks firmly and without damage to the material by contact therewith at the first station whereby the various operations may be performed on the gripped blanks without disturbing their positions on the carriers. After

each blank has been gripped by its respective carrier element it remains fastened to this particular carrier until the box is completed. The small size of the suction cups permits gripping of thin sheets without deformation. In this connection, it has been the further object to provide elevating mechanisms for lifting the carriers from engagement with the chain at each station and for moving them to operative position with respect to the various forming mechanisms, these elevating mechanisms being synchronized with the movement of the chain.

It has been a still further object to provide carrier mechanism which embodies an endless conveyor chain having a series of carrier blocks fixed thereto along its length and a series of carriers, one for each block, the carriers and carrier blocks being component and adapted to be disconnected for independent movement of the carriers to the zone of the operating mechanisms and return thereof to the carrier blocks and further the carriers being rotatable in the blocks for purposes hereinafter described.

It has been a still further object to provide for the trimming of the blank prior to its entry to the first wall forming station and in the trimming operation to define sealing flaps at the ends of opposite side walls. In this connection, it has been the object to provide that the first wall forming station, in addition to forming the opposite side walls of the box, also crimps and defines the sealing flaps at the ends of the other side walls.

It has been a still further object to provide adjacent wall forming stations, the first of which forms the opposite side walls of the box and the second of which forms the remaining side walls of the box, with indexing mechanisms between these stations for rotating the blank by rotating its carrier through ninety degrees after the first pair of side walls are formed so as to dispose the unformed side portions of the blank in position for engagement and formation by the dies at the second of these stations, the dies of the two stations being in alignment longitudinally of the machine.

It has been a still further object to provide for the completion of the box at a final station in the machine, at which station the partly completed box is nested upon a forming block, the first two side walls are clamped in position, solvent is applied to their vertical end margins, and following this the other side walls are clamped in position and the sealing flaps turned around the corners of the box and adhesively joined with said end margins prior to which the solvent applying mechanism is withdrawn. Preferably an acetone solvent is applied which dissolves the plastic enough for causing the flaps to unite or merge with the margins over those areas of the margins to which solvent is applied.

It has been a still further object to provide means for discharging the completed boxes successively from the forming block, wherein the boxes are ejected from the block by means of plungers which are air actuated to displace the boxes from the block and wherein the air leaking through the plunger bores breaks any vacuum which would tend to hold the boxes on the block.

It has been a still further object to provide means in the block for holding those side walls which carry the flaps clear of the other side walls while the adhesive is being applied, those means which retain the walls clear as described, 75

being easily depressible out of the way in the final stages of the forming operation.

It has been a still further object to provide a drive shaft arrangement driving all of the mechanisms from the base of the machine, to provide forming mechanisms at the various stations above the conveyor chain and to employ elevating means which act substantially simultaneously throughout the stations to raise the carrier elements from their connections with the chain to positions for action on the blanks by the various forming mechanisms.

It has been a still further object to provide mechanism for intermittently moving the chain, 15 which mechanism is effective for rigidly holding the chain and the various component parts, in which the carriers are transported, in rigidly fixed positions so that they cannot move and become displaced and will thereby be in position 20 for re-entry of the carrier elements as the elevating mechanisms are lowered.

It has been a still further object to provide an effective apparatus for applying the solvent along the vertical end margins of the opposite 25 sides of the box. The solvent applying mechanism has the solvent delivered therefrom by gravity and carried to the solvent applying surfaces through porous material which will retain and hold an adequate amount of solvent for the proper application of a measured amount of solvent to the walls of the box, the apparatus including a vacuum means for drawing off all excess material from the porous applicator surface whereby there can be no dripping of solvent or smearing resulting from the application of too much solvent.

It has been a still further object to provide for accurate adjustment of all parts of the machine which handle the blank so that the size 40 of the blank may be varied and therefore the size of the box manufactured by the machine changed to suit the requirements of the user. These adjustments are provided throughout the machine from the feed reel to the final forming block.

Other objects and certain advantages of the invention will be more fully apparent from the following description of the drawings, in which:

Figure 1 is a general side view of a receptacle or box-forming machine embodying the features of the present invention.

Figure 2 is a plan view of the blank from which the box is formed, showing it as a projection of the blank as disposed at Figure 1 where it is positioned in the first or starting station.

Figure 3 is a plan view of the more advanced blank, showing its form after it has been operated upon at the second or trimming station.

Figure 4 is a plan view of the blank after further progress through the machine, showing it after the side wall forming dies have operated upon it at the third or primary wall forming station of the machine.

Figure 5 is a plan view of the blank, showing it after it has been rotated and operated on at the fourth or final wall forming station at which time those sides opposite to the sides formed up at the third station have been bent or crimped into position.

Figure 6 is a plan view of the completed box as it appears after the operations are performed at the fifth or finishing station, this view, just as those previously described, being shown above

the machine as a projection in plan view of the box as it appears at the particular station.

Figure 7 is a fragmentary side view of the intake end of the machine, the view being enlarged for the purpose of illustrating the mechanism for feeding the plastic sheet from a roll to and through the first station.

Figure 8 is a fragmentary side view taken similar to Figure 7 but showing the feed mechanism being retracted after having delivered a portion of the sheet, sufficient for a blank, to the first station.

Figure 9 is a side view taken similar to Figure 8 showing the feed mechanism completely retracted and in position to begin a feeding stroke.

Figure 10 is a sectional view taken longitudinally and centrally of the intake end of the machine, this view illustrating the details of the feed rolls and the cut-off mechanism, the cut-off mechanism being ready to begin its cut-off stroke.

Figure 11 is a sectional view taken on the same plane as Figure 10 but showing the blank section fully advanced and the cut-off mechanism severing the section from the plastic sheet.

Figure 12 is a top plan view of the intake end of the machine.

Figure 13 is a sectional view taken on line 13-13, Figure 1, further illustrating the cut-off shears and showing the mechanism at the first station where the blank is received and secured to one of the carriers which conveys it through the machine.

Figure 14 is a fragmentary sectional view taken on line 14-14, Figure 8, detailing the feed rolls.

Figure 15 is a fragmentary sectional view taken similar to Figure 14, the view however being enlarged for the purpose of illustrating the intermittent clutches for causing feed for the upper feed roll.

Figure 16 is the diagrammatic view depicting the intermittent drive mechanism for the feed roll.

Figure 17 is a sectional view taken on line 17-17, Figure 15, detailing one of the clutches which is interposed between the feed roll and the drive for causing the aforesaid intermittent motion.

Figure 18 is a fragmentary sectional view taken on line 18-18, Figure 7, showing the mounting for the reel which carries the roll of plastic sheet, the view further illustrating the means for laterally adjusting the feeding reel.

Figure 19 is a fragmentary sectional view taken on line 19-19, Figure 14, illustrating the device for spreading the feed rolls when the plastic sheet is to be adjusted relative to the rolls.

Figure 20 is a fragmentary sectional view taken on line 20-20, Figure 19.

Figure 21 is a fragmentary sectional view taken on line 21-21, Figure 18, detailing one of the guiding devices for the feed reel.

Figure 22 is a fragmentary sectional view taken on line 22-22, Figure 21, further detailing the device of Figure 21.

Figure 23 is a fragmentary sectional view taken on line 23-23, Figure 7, showing in enlarged detail the adjustable crank arm which operates the feed rack.

Figure 24 is a sectional view taken on line 24-24, Figure 23, detailing the connection between the crank arm and the rack bar.

Figure 25 is a fragmentary sectional view en-

larged out of Figure 10 more fully illustrating the structure of the cut-off blade.

Figure 26 is a fragmentary sectional view enlarged out of Figure 11 showing the cutting blade in its cutting position.

Figure 27 is a sectional view taken on line 27-27, Figure 1, looking toward the second or trimming station of the machine and showing the parts employed in this station in general detail.

Figure 28 is an enlarged fragmentary top plan view of the second or trimming station of the machine.

Figure 29 is a sectional view taken similar to Figure 27 but showing the trimming dies at the completion of their upper or trimming stroke.

Figure 30 is a fragmentary sectional view taken on line 30-30, Figure 29, showing the form of the lower or movable die element.

Figure 31 is a fragmentary sectional view taken on line 31-31, Figure 28, showing the parts enlarged and particularly illustrating the means for laterally adjusting the dies.

Figure 32 is a sectional view taken on line 32-32, Figure 31, particularly detailing the die adjustment at right angles to that of Figure 31 and showing the details of the lower depressible die elements.

Figure 33 is a sectional view taken on line 33-33, Figure 1, looking toward the third station of the machine at which station the side walls of the container are formed.

Figure 34 is an enlarged fragmentary top plan view of the portion of the machine including the third or side wall forming station.

Figure 35 is a view taken similar to Figure 33 but illustrating the mechanism at its upper limit of stroke at which time the blank is folded to set up the side walls of the box.

Figure 36 is a fragmentary sectional view taken on line 36-36, Figure 35, detailing the mechanism which folds the side walls of the box.

Figure 37 is an enlarged fragmentary sectional view taken on line 37-37, Figure 36, illustrating the adjustment mechanism for the side wall forming elements.

Figure 38 is a sectional view taken on line 38-38, Figure 37, further detailing the mechanism.

Figure 39 is a fragmentary sectional view taken on line 39-39, Figure 34, showing the means for locking the parts in adjusted relationship.

Figure 40 is a fragmentary sectional view taken on line 40-40, Figure 1, looking toward the fourth or final side-wall setting up station which operates upon the blank after it has been rotated 90°.

Figure 41 is a sectional view taken on line 41-41, Figure 40, detailing the side-wall forming elements of this station.

Figure 42 is a horizontal, fragmentary sectional view taken on the same line as Figure 41, but including both the third and fourth stations and showing the indexing means for rotating the blank between these stations.

Figure 43 is a view taken similar to Figure 42, but showing the blank at the end of the indexing movement and as it enters the fourth station.

Figure 44 is a fragmentary view taken longitudinally of the machine between the third and fourth stations and indicating one of the carriers approaching the index block.

Figure 45 is a sectional view taken on line 45-45, Figure 44, the view showing in dot and dash lines the position of the carrier as it moves through the index block.

75

Figure 46 is a sectional view taken on line 46—46, Figure 45, further detailing the indexing mechanism.

Figure 47 is a sectional view taken on line 47—47, Figure 1, looking toward the fifth station or the station at which the box is completed.

Figure 48 is a top plan view of a portion of the machine, particularly showing the mechanism at the fifth station.

Figure 49 is a sectional view taken on line 49—49, Figure 1, showing in general detail the parts for completing the forming of the box.

Figure 50 is a sectional view taken on line 50—50, Figure 49, showing in top plan view the cam controlled clamping units which act upon the side walls of the box.

Figure 51 is a view taken similar to Figure 50 showing the mechanism in position with opposing side walls held against the central forming block and the other or laterally disposed side-wall clamping units prior to the beginning of their clamping movements.

Figure 52 is a fragmentary enlarged detailed view taken from Figure 51 and illustrating in detail the relationship and the parts of the respective clamping units.

Figure 53 is a view taken similar to Figure 52, but showing the laterally disposed side-wall holding or clamping units moving the side walls into position.

Figure 54 is a view taken similar to Figure 51 but showing the laterally disposed side-wall clamping units completely engaged upon the box with the exception of turning in the sealing flaps.

Figure 55 is a fragmentary view taken similar to Figure 52 and being enlarged out of Figure 54 but showing the final clamping action in the formation of the box.

Figure 56 is a view taken similar to Figure 54 but showing the sealing flap holding elements in final position.

Figure 57 is a view taken similar to Figure 52 but being enlarged out of Figure 56 for showing in detail the holding means for the sealing flaps.

Figure 58 is a sectional view taken transversely of the mechanism on line 58—58, Figure 50, this view showing the box held in final clamped position.

Figure 59 is a view taken similar to Figure 53 but showing the box being discharged from its position of final formation.

Figure 60 is a sectional view taken on line 60—60, Figure 59, further illustrating the structure in the central forming block which assists in discharging the box therefrom.

Figure 61 is a sectional view taken on line 61—61, Figure 60, further illustrating the box release or discharge means.

Figure 62 is a side view of the central forming block of Figure 61.

Figure 63 is a fragmentary sectional view taken on line 63—63, Figure 48, detailing the operating mechanism for one of the box wall clamping units.

Figure 64 is a fragmentary sectional view taken on line 64—64, Figure 63, showing further details thereof.

Figure 65 is a fragmentary top plan view, with certain parts broken away, illustrating, in particular, one of the four devices for applying solvent to the margins of the ends of the side walls.

Figure 66 is a sectional view taken partly on line 66—66, Figure 65, showing in detail the solvent applicator, the mechanism for supporting it, and the means for feeding the solvent thereto.

Figure 67 is a fragmentary sectional view taken on line 67—67, Figure 65, showing the means for holding the walls of the box in position while the solvent is being applied.

Figure 68 is an end view of an solvent applicator.

Figure 69 is an enlarged fragmentary, partly sectional view, taken from Figure 48 illustrating one of the lateral slides which carry the clamping units acting upon the side walls of the box.

Figure 70 is a fragmentary sectional view taken on line 70—70, Figure 69, further illustrating the slide.

Figure 71 is a fragmentary side view of Figure 70.

Figure 72 is a fragmentary sectional view taken on line 72—72, Figure 70, showing further details thereof.

Figure 73 is a fragmentary sectional view taken on line 73—73, Figure 72, illustrating in detail the fingers which press the flaps into position after the solvent has been applied.

Figure 74 is an enlarged sectional view taken on line 74—74, Figure 73.

Figure 75 is an enlarged fragmentary sectional view taken on line 75—75, Figure 73.

Figure 76 is an enlarged fragmentary sectional view taken on line 76—76, Figure 73.

Figure 77 is a fragmentary top plan view taken from the lower right-hand corner of Figure 51 for the purpose of more fully illustrating one of the means for pressing the sealing flaps into position.

Figure 78 is a fragmentary sectional view taken on line 78—78, Figure 47, illustrating the mechanism which permits intermittent drive of the sprocket chain carrying the carriers for the blanks.

Figure 79 is a sectional view taken on line 79—79, Figure 78, illustrating the clutch mechanism which disconnects the feed for the conveyor chain at the completion of the up stroke or forming movement of the mechanism at the fifth station.

Figure 80 is a similar view taken of Figure 78, but showing the indexing mechanism for the conveyor chain in operating position.

Figure 81 is a view taken similar to Figure 79, but showing the indexing gear connected as in Figure 80 and when the box completing mechanism is at its lower position.

Figure 82 is a fragmentary sectional view taken on line 82—82, Figure 80.

Figure 83 is an enlarged, partly sectional view illustrating one of the carrier mechanisms which convey the blanks through the machines, showing it coupled to the conveyor chain.

Figure 84 is a sectional view taken on line 84—84, Figure 83, further detailing the carrier.

Figure 85 is a fragmentary top plan view of the carrier.

Figure 86 is a view taken similar to Figure 83 but showing the carrier disconnected from the conveyor chain by virtue of the upward motion of the carrier.

Figure 87 is a sectional view taken on line 87—87, Figure 86, detailing the detent locking mechanism which holds the carrier in connection with the chain.

Figure 88 is a sectional view taken through the lower end of the carrier detailing its connecting means.

Figure 89 is a diagram in the nature of a graph showing the inter-relationship of the various movements and their synchronization.

11

The intermittent feeding movements of the chain are accomplished through a mechanism adjacent the fifth station (Figures 78 to 82 inclusive), this mechanism being effective for permitting feed of the carriers when the forming mechanism is at its lower position and discontinuing the feed when the forming mechanism is operating upon the box at its upper position. The mechanism for connecting and disconnecting the carriers to the index chain (Figures 83 to 88 inclusive) makes it possible for the chain to move to bring the carriers to positions where they can be picked up by the appropriate mechanisms at the particular stations and where they can again receive the carriers for further feed after they have been lowered by the mechanisms. The foregoing description is intended to describe the general structure without reference to the details. The following description will identify the initial blank feeding or delivery mechanism, the five stations and other associated apparatus, and will set out in detail the mechanisms employed at each.

Blank delivery mechanism

Referring to Figures 1 to 26, inclusive, of the drawings which illustrate the mechanism for delivering the severed blanks to the conveyor chain, the roll of plastic material is generally indicated at 100. This roll is mounted on a large spool or reel 101. The spool includes a central shaft 102 and side flanges 103. The shaft which traverses the collars 104 of the side flanges is supported at its ends in the grooves of bearing blocks 105 (Figure 7). These bearing blocks are fixed to lateral flanges 106 formed as a part of the side plates 107.

The side plates 107 are part of an adjustable unit, hereinafter described, which unit may be moved longitudinally of the machine on a base plate 108 (Figure 13). These side plates carrying the reel, the feed rolls, and the cut-off mechanism are slidably supported on this base plate 108. One plate 107 includes, for this purpose, a dovetailed connection 109 with the base plate. The other side plate 107 is held against the base plate by means of a guide plate 110 lying along its outer side and adapted after adjustment to lock the side plate to the base plate by means of screws 111. The guide plate 110 overhangs a flange 112 of the side plate. Another guide plate 110 is provided along the inner side of the other plate having the dovetail sliding connection which guide plate engages and holds the other side plate in the same manner as the one first described.

Adjustment of this reel carrying unit is accomplished by means of a cross shaft 113 having gears 114—114 fixed thereto, the shaft being journaled in the side plates 107—107 and including a square outwardly extending end adapted to be engaged by a suitable wrench. The gears 114—114 mesh with rack bars 115—115 fixed to the base plate. The plates are connected across their top at the inner side of the feed reel by means of a cross plate or supporting bracket 116 (Figure 12) which plate functions for supporting the cutting mechanism hereinafter described. The purpose of longitudinal adjustment of the feed roll unit on the machine is to provide that the delivered sections of the plastic sheet will be correctly positioned with respect to the sucker elements of the carriers which pick the blanks up as they are cut from the roll.

Inasmuch as it is important to keep the feed reel 101 aligned with the conveyor mechanism

75

12

so that the conveyors will grip the sheet accurately centrally of its width, suitable mechanism is provided for adjusting the reel laterally (Figures 18, 21 and 22). Also, it is necessary to prevent free spooling since the sheet of material would backlash. These requirements are filled by means of mechanism carried by a cross shaft 117 rotatively supported in the side plates 107. This cross shaft 117 is fixed against axial movement relative to the side plates by means of collars 118 fixed on the shaft and engaging the respective outer sides of the plates. The outer end of the shaft is square so as to receive a wrench for rotating the shaft.

Adjacent each side plate at its inner side there are provided adjustment blocks 120 traversed by screw-threaded portions of the shaft 117. These blocks have dovetailed connections at their bottom with a cross rail 121 fixed between the side plates so that they are guided for lateral adjustment and cannot rotate with the shaft. Each adjustment block includes a horizontal slot within which is mounted a contact roller 122. The axis of each roller 122 is parallel to the side of the respective side flange of the reel and therefore each roller has its periphery engaging the side flange of the reel. Thus these contact rollers will revolve upon contact with the side plates. In addition to centering the reel, that is properly aligning it with respect to the machine, these contact rollers when the proper adjustment is made contact the sides of the reel with sufficient pressure to prevent overfeed and therefore backlash when the feeding mechanism advances the sheet of material. This overfeeding can readily occur when the machine is being operated at high speed. In other words, a certain amount of drag or resistance is provided sufficient to resist the overfeed but which is not strong enough to interfere with the normal feeding or advancing movement of the feeding mechanism as hereinafter described.

The plastic sheet is fed by means of feed rollers 123 and 124 detailed in Figures 14 to 17 inclusive. The upper of these rolls, namely, 123 is driven. The plastic sheet passes between the rolls (Figures 10 and 11) and the lower roll 124 is adjustable under spring pressure toward the driven roll so as to provide a feeding contact which will not permit slippage. These rolls are journaled in the side plates 107. The upper or driven roll has counterturned bearing extensions 125 passing through and beyond the side plates. Each one of these extensions is equipped with a clutch unit generally indicated at 126.

The shaft is intermittently rotated through a gear 127 keyed to a drive shaft 128. This shaft 128 has its outer end journaled in a bracket 129 (Figure 13) and its inner end, which includes the clutch elements, is supported on the extending extension 125 of the feed roll 123. The inner or driven element 130 of the clutch is keyed to the extension 125 and includes a series of more or less tangential abutment lugs 131 (Figure 17). An outer or driving casing 132 encases the element 130 and is constituted as a fixed or integral part of the drive shaft 128. The outer end of the extension 125 is counterturned as at 133 and is rotatively journaled in a bore formed axially within the drive shaft casing member 132. For assembly purposes, the casing is formed of three parts fixed together as shown in Figure 15, specifically end plates and a cylinder. A series of roller elements 134 are disposed axially parallel with the shaft and adjacent the respective

General arrangement of the machine

The illustrated embodiment of this invention is designed for forming a rectangular box having a bottom and four sides and which is open at the top. It has been designed primarily for forming the box from a blank of plastic sheet material. In its initial stage, and reference may be had to Figures 2 to 6 for an understanding of the stages of construction, the blank is shown square, being constituted by cutting a length from a strip of sheet material. It will be understood that the blank may be rectangular if desired. The box structure passes through five stages including the initial blank, namely, the blank; the trimmed blank, in which the excess material not needed for the side is cut away; the partly formed blank wherein opposite side walls are primarily formed or turned, and sealing flaps are contemporaneously defined on the other side walls; the further formed stage wherein the other side walls are primarily set up or folded; and the final stage wherein the four sides are brought to a perpendicular position with respect to the bottom and the sealing flaps are engaged and fixed to the solvent coated margins of the adjacent side walls.

Thus, the machine may be said to include five forming stations corresponding to these stages of construction of the box and these will be referred to as the first or initial blank forming station; the second or blank trimming station; the third or primary side wall forming station; the fourth or final side wall forming station; and the fifth or finishing and sealing station.

The machine is of elongated structure incorporating a main body section which supports the various actuating mechanisms. This body supports the main shaft which carries the cams operating these various actuating mechanisms, the shaft being appropriately driven by a motor. A secondary frame structure is mounted on the body frame and this largely supports the various box forming mechanisms which are disposed along the machine above a conveyor chain mechanism which carries the blanks through the machine.

In describing the progress of the blank through the machine in general, it is pointed out that the plastic sheet is initially fed from a roll by means of a mechanism having its motion synchronized with the rest of the machine. As the strip is fed, a cutter mechanism is effective for severing an appropriate length therefrom suitable for the intended blank. As the blanks are severed, they are successively picked up and carried by means of a series of carriers on a conveyor chain extending the length of the machine. For this purpose the chain includes a series of receivers which hold and transport the carriers. The carriers hold the blanks by means of suction cups on the upper sides thereof. After each blank is fixed at the first station it is lowered through an appropriate mechanism to bring its carrier into coupled relationship with one of the receivers on the chain and thereupon the chain is moved to take the blank to the next or second station (Figures 27 to 32, inclusive).

At this second station the carrier is lifted from the chain, that is, disconnected therefrom by the upward or trimming motion of the trimming dies. The excess material not needed for the walls and bottom of the box is cut away and thereupon the carrier is again lowered to conveyor connection. The chain is again moved to bring the trimmed

blank up to the third station (Figures 33 to 39 inclusive).

At this station the laterally disposed margins of the blank are folded upwardly to constitute opposite side walls. Also, coincident with this operation the ends of the blank portions, which are to constitute the other side walls, are crimped or bent to form the attaching or sealing flaps. The same procedure occurs here, that is, the carrier is lifted out of engagement with the chain and after the wall forming and crimping operation is again lowered into connection therewith. From this point the blank is carried to the next or fourth station through a further movement of the chain (Figures 40 and 41).

However, intermediate these two positions, the blank is rotated by an indexing mechanism which swings it through an arc of 90°, thereby placing the previously formed side walls crosswise to the machine and disposing the remaining two sides in position for forming of the other two side walls (Figures 42 to 46 inclusive). After the blank with its side walls primarily formed is again lowered into connection with the chain through its carrier, it is again fed by further movement of the chain to the fifth or final forming station (Figures 47 to 77 inclusive).

Preferably, the material from which the boxes are made is a thermo-plastic material. With thermo-plastic sheet stock it is necessary to apply heat when bending or crimping to relieve the strains in the material so that the material will remain in crimped position, that is to say, the material will take a set and will not return to its previous position. Throughout the specification and claims the material is referred to as a plastic, and it will be understood that this is intended to have reference to thermo-plastic, the preferred material. In the operations performed at the third and fourth stations, that is, the wall forming stations, the male and female dies are effective for applying pressure along folding lines and, with the combination of heat and pressure application, the sheet is crimped and the side walls brought up to approximately their final position.

Actually, they are slightly inclined away from a truly perpendicular position, the reasons for this being more apparent later in the description. The term crimping will be understood to define this action wherever it is used throughout the specification and claims. The dies form a very slight groove in the material along the line of fold. This impression, which constitutes a bead or ridge along the edge of the box, adds greatly to the strength of the box.

At the fifth station the box is formed around a central block and holding dies are translated inwardly from the four sides to hold the sides in position while the sealing flaps are pressed into final position around the adjacent side edges. In this same side station solvent is applied to the margins, that is, to the margins of the ends of opposite side walls and forming fingers press the sealing flaps against these solvent coated margins. At the proper time, when the box is completed with the sides connected, a blast of air is effective for blowing the box from its completed position into a discharge chute.

The solvent is applied through four applicators, one for each corner of the box, which applicators are fed from a container for the solvent. The details of the applicators will be described later in detail and include means for drawing off the excess solvent and for insuring the application of a controlled amount of solvent in a uniform manner.

lugs 131 within the spaces between adjoining lugs and the surfaces of the inner and outer clutch elements. The surfaces of the inner clutch element indicated at 135 are eccentric relative to the axis of the shaft and the rollers are urged into the wedging areas, thus formed, by means of coil springs 136 disposed under compression.

The clutch unit 126 at the other end of the drive roller is a duplicate in construction to the one just described except that the casing 132 includes an outward extended circular flange 137 traversed by screws 138 which fix it to the side plate 107. Referring to this latter clutch, it will be apparent that as the feed roller is rotated in one direction, the feed roller will be rotated in a feeding direction, namely, counter-clockwise as viewed in Figures 1 and 17. When the shaft extension is rotated in the other direction, the feed roller will be locked against rotation and back feed of the plastic sheet is thereby prevented. These actions occur since the rollers of the clutch at the left-hand side (Figure 15) will, when the drive shaft 128 is rotated counter-clockwise, become wedged against the driven element and as clutched to it will cause feeding rotation of the roll. The feed roll is then effective for driving the inner clutch element in the other clutch unit, that is the one at the right-hand side of Figure 15, which has the reverse effect, that is the effect of loosening the rollers and permitting rotation of the feed roll relative to this latter clutch. When the drive shaft is rotated clockwise, the rollers in the left-hand clutch are loosened and any tendency of the feed roll to rotate is prevented since the inner clutch element of the right-hand clutch then tends to wedge the rollers into clutching engagement with the casing of the last named clutching unit.

The gear 127 is rotated by means of a rack 140 reciprocating by means of a crank arm 141 (Figures 7 and 23). The free end of the rack, that is the portion engaging the gear 127, is slidably supported in a cradle element 142 (Figure 14) which is pivotally suspended on the drive shaft 128 between the gear and the adjacent clutch unit. The other end of the rack is pivotally attached to the end of the crank 141. The bearing element 143 of the rack journals a pivot stud 144 therein, the inner end of the pivot stud being screw-threaded into an adjustable driving block 145 which is a part of the crank arm. As will be apparent from Figure 24, the driving block is guided for movement in a channel 146 formed longitudinally along the outer surface of the crank arm. The channel includes the usual dovetail for preventing lateral displacement of the bearing block.

An adjustment screw 147, parallel to the crank arm, is rotatively journaled in the end of the crank arm opposite to the adjustment block. The end of the crank arm is recessed as at 148 which provides a wall or flange 149 traversed by the shaft or adjustment rod. Retaining collars 150 are fixed to the rod at either side of the flange 149 and the outer end of the rod is squared to receive a wrench or crank handle. The other end of the rod 147 is screw-threaded through the block 145. Thus, by rotating the rod the adjustable driving block 145 may be moved longitudinally of the crank arm and the throw thereof is varied and accordingly the amount of feed of the plastic sheet is controlled. The crank arm has a drive shaft 151 fixed thereto intermediate its length. The adjustable driving block 152

may be moved from maximum throw at the outer end of the crank arm to a position of zero throw immediately adjacent the axis of the driving shaft 151.

Motive power is brought up to the crank arm from a general drive shaft 152 (Figure 7) mounted in the main frame 153 of the machine. The end of this shaft adjacent the input end of the machine is supported on bearing elements 154-154. The endmost of these bearings 154 includes a secondary bearing element 155. The shaft 152 carries a bevel gear 156 fixed thereto and meshing with a bevel gear 157 fixed to the lower end of a vertical shaft 158. The shaft 158 is mounted for rotation in the secondary bearing 155 and its upper end carries a bevel gear 159 fixed thereto and resting on the top of a bearing element 160 supporting the upper end of the shaft on the top of the frame 153. The bevel gear 159 meshes with another bevel gear 161 fixed to a horizontally disposed shaft 162 also journaled in the bearing 160. The outer end of this shaft 162 carries a bevel gear 163 meshing with a bevel gear 164 carried by the shaft 151. The shaft 151 is journaled in a bearing insert 165 fixed in a recess in the side plate 107. The shaft 162 has a splined connection with the gear 161 so that general adjustment of the feed mechanism assembly on the base plate 108 will not interfere with this driving train.

Thus it will be seen that the crank arm is continuously operated for reciprocating the rack and producing intermittent feed motion of the feed roll, the clutches of the feed roll preventing back rotation when the rack is performing a return or idling movement. In order to provide for proper feeding pressure between the feed rolls, the lower roll 124 is urged upwardly by means of adjustable bearing blocks 167 (Figure 14). These bearing blocks 167 have the bearing extensions of the lower feed roll rotatively journaled therein and are themselves guided in vertical guide-ways constituted by channeled recesses 168 in the side plates and removable guide plates 169-169 (Figure 20). Springs 170-170 pressing the bearing blocks upwardly are disposed in sockets in the side plates and have their upper ends engaging the bearing blocks.

When desired, as when an adjustment of the plastic sheet is to be made, the lower roller may be held away from the feed roller, this being accomplished by means of manually operated levers 171-171. These levers are fulcrumed on the side plates (Figure 19). The outer ends of the levers 171-171 rest upon the flattened surfaces of cam elements 172-172. The other ends of the levers include lateral extensions 173 engaging the tops of the bearing blocks. The cam elements 172 are fixed to a cross shaft 174 and the outer end of this cross shaft includes a handle 175 (Figure 7). Thus, rotation of the shaft by manipulation of the handle moves the lower feed roll from operative to inoperative positions.

As the strip is fed from the reel and through the feed rolls, sections are periodically cut from the strip to constitute the blanks making up the respective boxes. The cutting mechanism is generally indicated at 176 and consists primarily of a fixed lower blade 177 and a movable upper blade 178, best shown in Figures 10, 11, and 13. The lower blade 177 is fixed between the side plates 107 of the feeding assembly. It is supported in a channel formed in the outer face of a cross plate 179 being held therein by means of screws 180. The cross rail or plate 179 is supported on

lugs 182 projected from the inner sides of the side plates 107.

The upper cutting blade is supported on the lower edge of a slide 183. The cutting blade itself is secured within a cross channel at the lower end of the slide by means of screws 184. Its cutting edge is formed by chamfering the lower outer edge. The back surface and lower edge of this cutting blade come into snug contact with the outer upper edge of the lower stationary cutting blade 177. Likewise, it will be noted from Figure 13 that this movable blade has its lower longitudinal edge disposed at a slight angle to the cutting edge of the lower blade so as to procure a slicing or shearing action on the plastic sheet.

In order to make certain that the plastic sheet is held securely for the cutting operation a spring urged clamping bar 185 is mounted parallel with and in back of the upper cutting blade. This clamping bar is disposed within a channel 186 (Figures 25 and 26) with its lower edge normally projecting beneath the lower edge of the slide and beyond the cutting edge of the upper cutting blade. In order to retain the clamping bar in position when the cutting blade is in its upper position, that is, so that the springs 187 do not displace it from the channel, the channel includes a cross lip 188 at its lower end cooperating with a cross flange 189 on the clamping bar. The lip and flange are in engagement when the cutting blades are not performing a cut. The coil springs 187 are disposed between the upper surface of the cutting bar and the upper surface of the channel which contains the clamping bar.

The lower surface of the clamping bar includes a facing strip of rubber indicated at 190, this strip providing a contact surface which grips the plastic sheet against the upper surface of the cutting knife. As shown in Figure 26, the clamping bar engages the plastic sheet prior to the cutting operation, the cutting knife moving relative thereto as the slide descends. The slide is guided relative to the inner forward edges of the side plates 107 and is held in this guided relationship by means of plates 191.

Movement is imparted to the slide 183 through the following mechanism: A bevel gear 192 is fixed to the shaft 162 (Figure 7) and meshes with the gear 193 fixed to the lower end of a shaft 194 extending vertically along the side of the side plate 107. The side plate includes flanges 195-195 at right angles to each other which support the shaft 162 and the shaft 194. The upper end of the shaft 194 is supported in a lug 196 which forms a part of the cross plate 110 supported upon the respective side plates 107. A further shaft 197 is disposed horizontally between and mounted within lugs 198-199 formed on the top of the plate 110.

The outer end of the shaft 197 carries a bevel gear 200 meshing with a bevel gear 201 fixed to the upper end of the shaft 194. A cam 202 is fixed to the shaft adjacent the lug 199 and above the central portion of the slide. An actuating bracket 203 is fixed to a lug 204 centrally of the top edge of the slide and this bracket carries a roller (not shown) riding in the cam track of the cam 202. The track of the cam is formed so as to synchronize the cutting movement with the feed of the plastic sheet so that the blank is cut off when the proper amount has been fed and when the feeding mechanism is idle.

As shown in Figure 8, the feed roll is stationary, its operating rack starting to retract in the idling movement preparatory to the next delivery

of the plastic sheet. The plastic sheet blank which has been cut off is now disposed at the first station. As indicated, the severed blank is in the process of being gripped by the suckers arranged around the top of one of the carriers. The carrier elements are each generally indicated at 205. Since these carrier elements are conveyed through all the stations it would appear advisable to make clear at this stage their exact structure, and their inter-relationship with the operating mechanisms at the various stations as well as with the conveyor chain extending the length of the machine.

Carrier and carrier transport mechanism

For an understanding of the carriers and their conveyor mechanism, reference may be had to Figures 83 to 88 inclusive. Each carrier 205 consists of a stud 206 having a plug 207 at its lower end and a carrier head 208 at its upper end. The upper end or the head of the carrier is formed of three superposed members. The lower of these, namely 209 is square in plan view as are the others, and includes aligning pins 210, one at each corner extending downwardly therefrom and providing tapered lower ends. As will be evident from Figure 86, these pins are engaged into openings 211 in the carrier elevating plates 212 of the respective operating mechanism and thus when the elevating plates are raised and the pins so disposed, rotation of the carriers is prevented and they are held in a stabilized position. This element 209 is secured to the stud upon a counter-turned screw-threaded extension thereof and held in place by means of a nut 213. An intermediate element 214 is engaged upon the element 209 and fixed thereto. The sucker carrier plate is secured upon the member 214 and has a plurality, nine in this instance, of sucker or gripper members effective on the blank 216 when forcibly pressed against the suckers.

The coupling plug 207 is riveted to a plate 211 and these elements in turn are fixed upon a counter-turned lower extension 218 of the stud 206. Each of the elevating plates 212 carries a pair of lift springs 219 on its under side parallel with the path of travel of the conveyor chain and the carriers and parallel with the channel formed by the relationship of the elevating plates (Figure 84). These springs are attached at one end by screws 220 and provide a spring action between the under sides of the elevating plates and the top of the plate 217. They are effective, as shown in Figure 86, for maintaining the carriers in stabilized position in the elevating plates when the elevating plates are in upward travel or at upper position. The springs are curved so as to provide rounded contact with the top of the member 217, thus permitting the carriers to be moved longitudinally in the channel, the spring slipping from contact as the carriers move away. The plate 217 includes a pin 221 at each corner, these pins having a function which will be described later.

The carrier chain is generally indicated at 222 and consists of a standard sprocket chain moving around sprocket wheels 223 and 224 at the respective ends of the machine (Figure 1). The upper run of the chain is supported in and travels through the channel 225 of a guide rail 226. At spaced positions along the chain there are provided a series of carrier receivers 227 fixed to the chain by means of angle iron pieces 228 (Figure 84). These carrier receivers or socket members include laterally extending ribs 229 dis-

posed in grooves 230 along the upper portion of the guide channel 225. Guide plates 231 are fixed along the top of the rail 226 and overhang these ribs. Each of these carrier receivers includes a socket 232 for receiving the plug ends of the carriers. The plug end of each carrier includes an annular groove 233 and at ninety degree intervals circumferentially arranged, a series of detent depressions 234. Detents 235 disposed longitudinally of the block engage the stud at diametrically opposite points. The detents 235 are disposed in bores 236 formed longitudinally in the carrier block and employ the usual coil springs 237 under compression between the heads of the detents and plugs 233 closing the outer ends of the bores. The purpose of these detents will be more evident in the description of the indexing of the blank at a further stage of the machine. Two detents are employed for stability in holding the carriers after rotation through ninety degrees. The elevating plates 212 are the same throughout the various stations with respect to their function and co-operation with the carriers.

First or initial blank forming station

The mechanism employed at this first station is best illustrated in Figures 7 and 13. The main shaft 152 which is supported in bearings 154 in the lower frame or body 153 of the machine carries a cam 239 fixed thereto and disposed between the bearing elements 154-154. The track of this cam is engaged by the roller 240 of the pivoted lever 241. The lever 241 has its pivoted end supported on a pivot pin 242 mounted between the bearing brackets 154-154. Between the bearing brackets 154-154 at the center of the machine there is provided a bearing element 233 in which a vertically translatable rod 244 is slidably mounted. The lower end of this rod incorporates a laterally extended pin 245 disposed in the slot 246 in the end of the lever 241, thus providing a flexible connection between the pivot arm and the rod.

A square plate 247 is attached to the upper end of the rod 244 between nut elements 248 engaged upon the rod and abutting the upper and lower sides of the plate. Four rods 249 extend upwardly from this plate specifically from each corner thereof and these rods in turn are guided in a bearing member 250 mounted upon the top of the frame member (Figure 13). These bearing members 250 throughout the stations provide the support for the chain guide channel 226 which is fixed in grooves in the respective members. The pairs of rods at each side of the guide channel carry the elevating plates 212 on their upper ends, these plates being normally disposed at a plane just above the chain track, that is when the elevating plates are not in upper positions for permitting the formation of the box structure at the respective stations.

As previously described, these elevating plates 212 act upon the particular carrier 205 as it comes up to the first station. As they are elevated by the cam 239 they pick up the carrier by coming up under it. The indexing pins 210 fix the carrier in positive non-rotative position with respect to the plates. At this first station (Figures 10 and 11) the synchronization of the machine causes the elevating plates to pick up the particular carrier 205 just prior to the operation of cutting off the blank from the main strip of plastic. The elevating plates are effective for

bringing the carrier upwardly and pressing the end section of the plastic sheet against an abutment arm 251 which is fixed to the end of the upper frame 252. This engagement of the end section of the plastic sheet under pressure against the foot or pad 253 of the arm 251 causes the suckers to grip the plastic sheet firmly. Immediately following this operation the section is cut off and the blank is then under the full control of the carrier to which it is attached. Referring back to the elevating plates 212, it is pointed out that they extend longitudinally of the machine between the respective pairs of rods which support them, being mounted on elements 254 which provide flanges disposed horizontally and fixed to the under sides of the elevating plates.

Second or blank trimming station

The mechanism employed at this station is illustrated in Figures 27 to 32 inclusive. Later on in the description, specifically in reference to the fifth station, the mechanism for causing intermittent motion of the chain for moving the carriers from one station to the next will be described. As the respective carriers are moved through the machine, they are transferred in a continuous motion from one station to another whereupon the chain pauses long enough at the stations to permit the mechanisms of the particular stations to function in setting up the box. Quite obviously, there are five blanks being operated upon at one time in the machine, each being in a different state of completion from the blank form to the completed box. As each blank is brought up to the second station, its carrier pauses for the operation just above the elevating plates 212 of the station. It is needless to describe the cam and operating mechanism and supporting means for the elevating plates at this station for the mechanism is identical to that employed at the first station. The variations in structure occur above the elevating plates.

Above the elevating plates there is provided a mechanism for trimming the blank, this mechanism being operated by the elevating motion of the plates which is effective for actuating certain of the trimming elements to trim the blank which is then disposed within the trimming mechanism. The trimming mechanism is primarily supported on a cross plate or supporting frame element 255. This cross plate is suspended on brackets 256, one at each side of the machine which brackets are attached to the inner surface of the upper frame section 252. An adjustment screw supporting bracket 257 is fixed centrally of the cross plate, the walls of this element supporting the adjustment screws 258 at their inner or adjacent ends.

The adjustment screws 258 extend crosswise of the machine and in axial alignment. Each has a bevel gear 259 fixed to its inner end within the support bracket 257. Abutment collars 260 are fixed to the screws and lie against the outer walls of the bracket and therefore, in conjunction with the bevel gears, prevent axial displacement of the adjustment screws. A short vertical adjustment shaft 261 extends through the upper side of the bracket and has a bevel gear 262 on its lower end within the bracket meshing with both of the gears 259. A collar 260 is also included on this shaft. The upper end of the shaft is squared so as to receive a socket wrench or the like for manual adjustment of the adjustment screws. The outer ends of the adjustment screws are threaded into adjustment blocks 263. These

blocks include flanged lower ends 264 which are bolted to the upper surfaces of the supporting plates 265 which carry the upper dies 266. Lower dies 267 are mounted in guided relationship to the dies 266 in a vertical direction. The supporting members 265 include dovetail grooves 268 along their upper surfaces crosswise of the machine and are mounted for sliding motion on the cross portions of the main cross plate 255 (Figure 32). Thus, the die elements may be adjusted as pairs laterally of the machine and toward and from each other to accommodate for variation in the size of the blank.

There are four sets of dies, these dies being disposed for operation upon the respective corners of the blank and therefore being arranged in rectangular relationship. Each of the upper die elements 266 includes a dovetail groove 268 in its upper surface longitudinally of the machine, these dovetail grooves in turn being in engagement with corresponding dovetail portions on the die supporting plates 265. The upper dies include male portions 270 fixed to their undersides, each of these portions being of a shape which will provide the proper cutting edge for removing the corner sections of the blank (Figure 3). Specifically, it is pointed out that they are square with the exception of sharp tabs or corner extensions 271 (Figure 30) at their innermost corners. In other words, in addition to cutting out a corner of the blank they cut a notch 272 (Figure 3) having an angular side 273 and thereby defining the tabs 274 which make up the sealing flaps 275 in the final box.

The lower or female die elements 267 are supported directly on the elevating plates 212 but are in guided relationship with the upper or male die elements. This guided relationship is accomplished by means of pins 276 rising from the lower die at its two outer corners and traversing vertical bores in the upper dies. Thus, any adjustment of the upper die is effective for adjusting the lower die with it. In other words, they move in adjustment as a unit, adjustment movements sliding them laterally on the elevating plates. The lower or female die elements are inclusive of openings 277 which contain depressible plates 278 (Figure 32). These openings conform in size to the shape of the male die extensions so that they will mate and be effective for shearing the excess material from the corners of the blank. It will be apparent from Figure 27 that each blank is brought into position between the dies when the dies are fully separated.

The depressible plates 278 are supported within the openings in the lower dies by means of coil springs 279, there being four of the springs, one at each side of the plate. Pins 280, one at each corner of the plate extend downwardly into bores in a mounting member 281 fixed in the bottom of the opening in the die. The lower ends of the pins are headed and the bores counterturned to receive the heads and to guide the pins. Thus, when the lower die elements are brought up against the material of the blank and the excess material is cut away, the male die elements enter the openings depressing the plates 278 and shearing the material. The cut-away material may be blown from the dies after separation by means of air delivered through jets generally shown at 282. In order to further support the blanks laterally during this process, inwardly extending support elements 283 are provided, these extending inwardly to points adjacent the central line of the blank.

Provision is made (similar to that for lateral variation previously described) for longitudinal relative adjustment of the dies so that they may be spaced to accommodate blanks of varying dimensions lengthwise of the machine. This adjustment mechanism consists, for each pair of die sets, of an adjustment rod 284 extended downwardly vertically through each of the adjustment bearings 263 and through the cross plate 265. Each adjustment rod includes a square upper end for receiving a socket wrench and has a collar 285 fixed to its upper end for supporting it against axial displacement. The lower end of the rod carries a bevel gear 286 meshing with a bevel gear 287 fixed to an adjustment screw 288 extending longitudinally of the machine, having its outer ends threaded into adjustment elements 289 fixed within the male die elements. A bracket 290 supports the adjustment screw 288 adjacent the gear 287, the bracket being fixed to the under side of the die support plate.

Thus, by adjustment of the adjustment rods 261 and 284, the dies may be adjusted not only laterally of the machine but longitudinally as well for varying their spacing.

Third or primary wall forming station

The structure incorporated at this station is illustrated in Figures 33 to 39, inclusive. The operating mechanism for the elevating plates at this station is identical to that disclosed in the previous stations. Here the trimmed blank is operated upon to produce the crimping or folding shown in Figure 4 which illustrates the third stage of the box. Certain of the elements in this mechanism correspond to those of the previous station and for this reason they will, wherever identical, bear the same numbers. This mechanism consists of longitudinally disposed upper and lower die elements 303 and 301 respectively. These sets of dies are laterally adjustable toward each other by means of an adjustment screw mechanism identical to that of the previous station.

The bearing blocks 263 are fixed to the upper die supports by means of screws 302 extending upwardly through the upper die carrying plates 303. These die supporting plates 303 include downwardly extending bosses 304. The guide pins 305 of the lower die plates 301 vertically traverse these bosses, whereby as in the previous structure the upper and lower dies may be adjusted as units. The upper die elements 303 extend longitudinally of the machine and in parallelism. They are adjustively spaced a distance equal to the predetermined width of the bottom of the box, the bottom of the box being indicated at 306 (Figures 4 and 37). The upper die elements are plate-like in form being of vertically disposed elongated structure. Their outer surfaces 307 are inclined slightly in an outward direction from their lower ends upwardly so that their lower ends present longitudinal edges which are substantially pointed but very slightly rounded as indicated at 308. The upper ends of these die plates are secured within channels 309 formed along the inner side edges of the supporting plates 303. They are attached by means of screws 310.

The lower die elements 301 are elongated as shown in Figure 36 so as to provide supporting surfaces of a length appropriate to the size of the blank. Immediately adjacent the forming edges 308 of the upper dies, the lower dies include longitudinal grooves 311. These grooves co-

operate with the upper dies when the elevating plates move the lower dies upwardly to crimp the material of the blank as at 312 and to cause the outer portions of the blank to be bent upwardly to form the sides 313 of the box. The crimping is very slight, that is to say the groove is very fine. The effect however, is to make a permanent bend in the material under considerable pressure. In the preferred form, the plastic is heated to aid in the folding by means of heating units placed in the bores 314 of the upper dies. The application of heat tends to make the plastic material more pliable and to more firmly set it in permanent position. The longitudinal edges 308 of the upper dies are effective for forming ridges or beads in the plastic at the fold lines and this adds to the strength of the box.

It will be noted from Figure 4 that this station is not only effective for forming the side walls 313 and defining the bottom 306 but also is effective for forming the sealing flaps 275 by crimping the material at the ends of those portions which subsequently form the other side walls. In other words, the crimping line extends beyond the side walls 313 and across the corners of the notches 272 formed in the trimming operation.

The adjustable die supports 303 are fixed in position, after adjustment, by means of a manually rotated tightening screw 315. This arrangement, as shown in Figure 39, includes a clamping element 316 disposed in the guide groove for the respective adjustable support plate.

Thus, it will be seen that at this intermediate stage of formation of the box, the blank, after another of its intermittent movements, has paused at this station to be elevated to the forming mechanism, there operated upon and there lowered for movement to the next station.

Fourth or final wall forming station

As illustrated in Figures 40 and 41, this next station is effective for forming the other two side walls indicated at 317 (Figure 5). In between these stations there is provided an indexing mechanism which is effective for rotating the carrier and its blank through an arc of ninety degrees and thus disposing the unformed side portions of the blank, which are to make up the side walls longitudinally of the machine, in the proper position to be acted upon by forming mechanism of the same general character as that described for the third station. The mechanism employed at the fourth station is almost a duplicate of that used at the third station. The only difference resides in the fact that the dies are not effective for forming sealing flaps but rather they simply indent and form the material to bend up the additional side walls along a bending line aligned with the end edges 318 of the other side walls 313. It will be noted that in this form as in the previous form, the lower dies are varied as to thickness by means of a series of laminations 319 attached against their under sides. This is done in order that the elevating plates will move these lower dies to an exact position for applying a definite predetermined degree of pressure to the material for crimping and forming up the side walls.

Indexing mechanism for rotating the carriers

As the carriers travel from the third station to the fourth station, that is between those points

where the primary wall forming operation is performed and the final wall forming operation is performed, it is necessary to change the position of the blank (Figures 42 and 43). As the blank leaves the third station its side walls 313 and the sealing flaps 275 have been set up longitudinally of the machine. The indexing mechanism is effective for disposing these formed side walls crosswise to the machine and thus disposing the margins of the blank to be formed into the additional side walls in parallelism with or in alignment with the forming dies.

For the purposes just described, an indexing block 320 (Figures 44 to 46 inclusive) is mounted on the guide rail 226. A plate 321 disposed vertically along the side of the rail carries the index plate 320 at its upper end, the parts being secured together by means of screws 322. The lower end of the plate is secured directly to the rail by means of screws 323. These screws traverse a spacer block 324 interposed between the side plate and the rail. The underside of the index plate 320 includes a cam groove 325. This groove is located so that the pin 221 on the adjacent corner of the carrier will enter it as the carrier is moved along the rail. This will be evident from an inspection of Figure 45 which discloses the path of travel of the carrier with respect to the block.

As the carrier moves alongside the block, the pin 221 rides in the cam groove. The groove is in the form of a flattened V, the apex thereof being disposed a distance from the center of the carrier or the chain equal to the distance from the center of the carrier to the center of the pin 221. Thus, the movement of the outer corner of the carrier is retarded and with the more rapid movement of the center of the carrier, the result is to swing the carrier, causing it to leave the block with the carrier rotated a full ninety degrees. The detents 235 (Figure 87) are effective for causing the rotation to be accurately defined at ninety degrees. In other words, the carrier will automatically move to a position where it is squared up with the track due to the tendency of the detents to snap into the depressions, thus causing an accurate indexing. Figures 42 and 43 illustrate the swinging movement of the blank. In Figure 42, the blank is at an intermediate position, whereas in Figure 43, it has almost reached the full index position with the side marginal portions of the blank to be formed into the additional side walls, properly disposed with respect to the forming dies of the next station.

Carrier Transporting Mechanism

The construction of the mechanism for transporting the carriers will be evident by reference to Figures 1, 47, and 78 to 82, inclusive. The sprocket chain, previously indicated at 222 and as stated, travels between sprocket wheels 223, 224. The sprocket wheel 224 at the intake end of the machine is supported for rotation on a shaft 330 (Figure 11), the shaft being sustained in bearing members (Figure 13) indicated at 331. These bearing lugs depend from the rail element 226. The shaft 332 (Figure 47) which mounts the other sprocket wheel 223 at the discharge end of the machine is driven intermittently for moving the carriers as previously described.

As indicated in Figure 47 this shaft is supported in the spaced vertically disposed lugs 333 of the member 334 which supports the rail 226 and guides and supports the elevating plate operating

mechanism at the fifth station. The shaft extends laterally and includes a splined outer end 335 upon which a gear 336 is slidably mounted. This gear 336 is adapted to be moved back and forth between meshed position with a movable rack bar 337 and meshed position with a fixed rack bar 338. The movable rack bar is disposed vertically between the upper and lower bearing members 339 and 340 respectively and is reciprocated from the main drive as described herein-after. The upper bearing 339 includes a vertical channel 341 within which the reciprocating rack bar is mounted. Alongside this movable rack bar (Figure 78) a short section of rack bar 338 is fixed to the bracket by means of screws 342. This latter rack bar overhangs the movable rack bar, fitting in a channel in the side thereof and thus holding the movable rack bar in guided position.

Movement of the gear between the two racks 337, 338 is accomplished by means of a clutch yoke 343 fixed to a pivot shaft 344. The clutch yoke has its pins 345 (Figure 80) entering a groove 346 in the hub of the gear at diametrically opposite points in the conventional manner. The pivot shaft is journaled in lugs 347 of the bracket 339 and is held against axial displacement by means of outer collars 348. The shaft is rotated for moving the gear back and forth by means of a crank arm 349 having one end fixed thereto and the other end coupled to a link 350 by means of a pin 351. The link 350 has its other end connected to a lug 352 extending downwardly from the elevating plate 212 of this particular station, the connection being by means of a pin 353.

The bracket is more fully illustrated in Figure 82, being secured to the body structure and depending through an aperture 354 therein. The bracket is provided with a clearance opening for the parts generally indicated at 355. Thus it will be apparent that the up and down movement of the elevating plate will cause the gear to move from the stationary rack to the fixed rack or vice versa. In other words, when the elevating plate is in upper position, the gear is locked with respect to the frame of the machine by engagement with the stationary rack 338 and movement of the movable rack which is an upward motion at this time is an idle or return movement. When the elevating plate is down (Figure 47) and no work is being performed on the blank, the gear is coupled to the movable rack and the carrier chain is translated.

The movable rack is translated by means of a segmental gear 356 (Figure 47). This gear is formed on the end of a fulcrumed lever 357 which is mounted on a pin 358 provided, fixed between the lugs 359 of the cross bearing members 360 at the base of the machine. The other end of the lever from that which carries the segmental rack is moved by means of a link 361 coupling the end of the lever to the outer end of a cam actuated arm 362 having its other end pivotally mounted on the end of the bracket 360 by means of a pivot pin 363. The pin and roller 364 disposed intermediate the length of the arm 362 engages the cam track of a cam 365 fixed to the main drive shaft of the machine. The lower bearing 340 for the reciprocating sliding rack is located immediately adjacent the point at which the segmental gear 356 meshes with the rack bar and thus the bearing takes up the thrust. The rack is held in the guide groove 366 in the bearing by virtue of the engagement of the segmental gear therewith.

In the operation of the machine, the conveyor chain will be driven when the elevating plates are at lower position. In other words, the cam track provides for intermittent movement of the rack, a cycle consisting of a driving movement for the chain from the position of the rack shown in Figure 47 at which time the rack is about to start downwardly to feed the chain. As the segmental gear reverses upon completion of this feeding movement, it starts to move the rack upwardly which would reverse the movement of the conveyor chain, the elevating plates begin their upward movement which uncouples the gear 336 from the movable rack and fixes it to the stationary rack. Accordingly, the up movement of the rack bar 337 is idle. When the work has been performed on the particular blank at the stations and the elevating plates move downwardly, the gear 336 is again coupled, at which time the rack has returned to the position shown in Figure 47 and is ready to start the next cycle. The purpose of fixing the gear 336 to the stationary rack, when the chain is at stationary positions and the elevating plates at upward positions, is to lock the chain against any movement whereby the carriers will re-engage the carrier blocks on the chain accurately and in alignment when they are lowered.

30 *Fifth or box completing and sealing stage*

The mechanism employed at this station is illustrated in Figures 47 to 76, inclusive. As in the previous stations, the carriers are successively brought up to the station and the conveyor chain 35 pauses or dwells at the station long enough to permit the elevating mechanism to raise the partly completed box, in each instance, to the plane at which the steps of completing the box are performed. The elevating mechanism at 40 this station is the same as that in the previous four stations. Therefore, it will be unnecessary to describe the mechanism at this station which is disposed at the plane of the elevating plates or below them, with the exception of the driving mechanism which extends upwardly from the main drive shaft 152.

A shaft 368 (Figures 1, 47 and 48) extends vertically upwardly from the drive shaft 152 and is driven therefrom by means of meshing bevel gears 369, 370 respectively fixed to the shafts 152 and 368 (Figure 1). A bearing bracket 371 supports the lower end of the shaft 368. This shaft 368 at its upper end is supported in a square bearing plate 372 supported on vertical standards 373 forming a part of the upper framework 252. The plate 372 includes a series of ribs 374 on its upper surface which serve to strengthen and stiffen the same which ribs have the added function of guiding elements as hereinafter set out.

60 In one corner of this plate 372 a boss 375 is included and the shaft 368 is rotatively mounted in this boss. A gear 376 is fixed to the upper end of the shaft and meshes with a large gear 377 axially mounted centrally of the plate on a stub shaft 378 (Figure 49). The stub shaft 378 is fixed to the gear and extends downwardly into a blind bore 379 formed centrally of the body 380 of the rectangular forming block 381. The body 380 is fixed to the central portion 382 of the plate 372 by means of long screws 383 extending upwardly through the body into the central portion. These screws are disposed around the stub shaft. The stub shaft is counter-turned to provide a shoulder 384 which rests upon the shoulder afforded by a counter-turned portion of the cen-

tral portion 382. The main body 380 of the forming block may be made of wood. Inserts 385 are provided at each corner. Thus, the size of the main body may be varied for boxes of different sizes and the inserts 385 may be standard.

The large gear 371 has its under surface supported flush with the upper surface of the main bearing plate 372. The large gear constitutes a cam element for operating the various forming mechanisms and for this purpose has two cam tracks 386, 387 inner and outer respectively. The shape of these cam tracks determines the synchronization and coordination of the movements. There are four movements or mechanisms operating relative to the central block and each of these includes a cam engaging pin and roller 388 projecting upwardly into the cam tracks. Figures 51 to 57, inclusive best illustrate the synchronization of these movements. The forming mechanisms at this station are adjustable in accordance with box size as at the previous stations. As stated, it is for this reason that the body 380 of the forming block is constructed of wood. A number of these bodies 380 are provided of different sizes. The inserts 385 at the respective corners are standard and accordingly the cut-out portions at the corners of the wooden block are also always of the same size. When the box size is to be changed, an appropriate body 380 is selected, the inserts are removed from the previously used block and are inserted in the new one.

Each of the mechanisms which operate on the sides of the box is in the nature of a slide generally indicated at 390. Those slides operating upon the laterally disposed side walls are duplicates and those operating on the sides which are disposed crosswise of the machine are duplicates. Accordingly, a description of one of each pair will suffice. In the synchronization of the mechanism, the mechanisms which operate on the walls disposed crosswise of the machine operate first in the cycle and accordingly will be described at this point. As stated, the square plate or support 372 for this mechanism includes ribs which reinforce the plate and certain of which guide the slides 390. Those ribs which guide the slides 390 acting upon the cross walls of the box are indicated at 391. For a clearer understanding of these mechanisms reference may be had to Figures 63 to 68, inclusive.

Each slide 390 of the particular mechanism being described is disposed for horizontal sliding motion longitudinally of the machine in dovetail guideways 392 constituted along the inner walls of the ribs 391. The roller and pin 388 extend upwardly from the top of this slide and engage the inner cam track 386. Thus timed reciprocation is imparted to the slide for moving it toward and from the central box forming block. The actuating mechanism which is suspended from this slide is adjustable in order to provide for the manufacture of boxes of different sizes.

For the above reason, the underside of the main slide 390 includes a dovetail groove 393 (Figure 64) within which is supported and adjustably mounted an adjustment block 394. An adjustment screw 385 extends longitudinally of the slide within the dovetail groove 393 and traverses the adjustment block 394. This adjustment screw is rotatively journaled in a support element 396 fixed to the outer end of the slide. Axial displacement of the screw is prevented by means of collars 397. The outer end

of the adjustment screw is squared to receive an adjustment wrench. Thus, the entire mechanism supported by this adjustment block may be altered as to position to accommodate for box size.

A still further adjustment is necessary to accommodate for size of box and this is with respect to the spacing of the units 398 which engage the end margins of the walls for holding them tightly in position and for applying the adhesive along the margins. Obviously, if the width of the box is altered, these marginal engaging elements must be moved in and out laterally of the machine. For this reason, a supporting bar 399 is fixed to the under side of the element 394 and thus lies crosswise of the machine beneath the main supporting plate 372 (Figures 63 and 64). Attachment of this cross-supporting bar is by means of screws 400 extending upwardly through the central portion of the bar into the element 394. It is pointed out here that appropriate gib plates 401 are provided for all of the dovetail slide surfaces, these being slightly tapered in the usual fashion to take up any looseness between the elements.

Each of the units 398 is of the following construction: A body 402 includes a dovetail groove 403 (Figure 67) crosswise of its upper surface which dovetail groove is in engagement with a dovetail formation 404 extending the length of the under side of the bar 399. A clamping or wedging element 405 within the dovetail groove is provided and is set in fixed position by means of set screws 406. As shown in Figure 67, the elongated vertically disposed holding pads or presser bars 407 are supported at their upper and lower ends by means of rods 408, these rods slidably traversing and being mounted in the body 402. The box engaging face of each presser bar 407 is covered with a facing of rubber or the like for holding purposes. Coil springs 409 are disposed under compression between the presser bar and the base of a counterbore or socket 410 forming a part of the bore in which the rod is slidable. The end of each rod includes a stop collar 411 fixed thereto and slidable within a counterbore 412. These collars limit the spring activated movement of the presser bars in an inward direction. When the pads come into contact with the side wall of the box for holding the wall against the central block (Figure 52), the springs are compressed and therefore the holding action is under spring pressure.

Directly alongside of the compressible pad or presser bar mechanism is slidably mounted the solvent or adhesive applying unit 413. Each of these units consists of a T-shaped (in side view) main element 414. The head of the T is disposed vertically parallel with and alongside 60 of the presser foot bar 407 and is indicated at 415. The shank of the T extends through and is supported in a groove 416 formed in the outer side wall of the supporting body 402. Anti-friction ball bearing units are provided between the shank and the upper and lower walls of the groove 416 to permit easy movement of the unit 413. The ball bearing units consist of a series of balls 417 confined against displacement by means of a perforated plate 418 lying between the unit and the supporting body 402. The balls lie in adjacent V-shaped grooves 419 in the shank and the upper and lower walls of the grooves respectively.

In order to provide a yielding action for each unit 413 acting in the same manner as the presser

bars 407, the same general arrangement is utilized, that is the combination of the rods 408, the springs 409, and the guided mounting of the rods in the body 402, is provided above and below the shank of the unit 413. The only difference is with respect to the outer ends of these rods. In the instance of the solvent or adhesive applying units 413, they include contact heads 429 centered by axial relationship with bores 421 in the inner face of the shank of the T-shaped element.

The solvent is supplied to the face of the unit 413 through the following system: A reservoir is provided (Figure 66) at 425, consisting of an inverted jug-like container resting in a cup 426. The cup includes grooves 427 in its upper edge which edge surrounds the spout 428 of the jug or bottle and engages the under side of the bottle. The level of the solvent is maintained in the cup as at 424. From the bottom of the cup a conduit 429 extends vertically downwardly. This conduit or pipe is rigid and is clamped within a bracket 430 by means of a set screw 431. This bracket may be fixed to a standard 432 fixed to the machine. From the lower end of the pipe 429, flexible tubing 433 extends to the inner end of the T-shaped element constituting the solvent applying unit. This flexible tubing is attached by means of a fitting 434 to the end of a bore 435 extending longitudinally of the shank of the T-shaped element to its head end and there extending upwardly as at 436.

At the upper end of the T the vertical extension 436 extends outwardly to communicate with a vertically disposed distributing bore 437 adjacent the face of the element. A series of apertures 438, horizontally disposed, connect this bore to a groove 439 in the face of the element. At the lower end of the T this outer groove is connected to a bore 440 by means of a cross-connecting passage 441, this bore connecting at its upper end to an outlet passageway 442 sloping downwardly slightly relative to the inlet bore 435. The outer end of this bore 442 is connected through a coupling 443 to flexible tubing 444 which extends to and is connected to a discharge tank or a sump 445. The connection is to the top of the sump. The excess solvent is drawn away from the unit by means of a suction creating pump unit 446 attached by a conduit 447 to the top of the discharge tank. The pump is conventional, being of the diaphragm type including a lever 448 actuated by a cam 449 continuously driven from some point in the machine.

In order to provide for the contact application or daubing of solvent through the elongated contact face of the unit, all of the passageways in the head of the T-shaped element and back part way into the passageways 435 and 442 are filled with a mass of minute spherical elements which are sintered together. The powder constituted by the minute spherical elements is poured into the cavity and is then sintered in an oven at a controlled atmosphere without the application of pressure.

In order to provide a definite elongated contact face, these spherical particles are mounted in the groove in the face of the T-shaped head so as to protrude slightly therefrom to form a projected solvent applying face of narrow elongated form. This face will engage the vertical end margin of the particular side wall. Thus, the solvent is delivered under the force of gravity, and all excess is drawn off by suction. This eliminates any possibility of drippage of excess solvent from the 75

unit. The formation of spherical balls is highly porous or sufficiently so for the maintenance of a proper supply of solvent at the contact face. Thus, the outer face of each unit is in effect an applicator, applying by direct contact a controlled and measured amount of solvent. Each of the units at the end of the bar 399, as above described, includes a cam member 450 projecting outwardly laterally therefrom and having a function hereinafter described.

Thus, it will be seen that these mechanisms above described will be effective upon the walls of the box which are disposed crosswise of the machine and that as they are moved simultaneously toward the central block the pressure bars or holding elements will first come in contact with the walls upon vertically disposed areas adjacent the end margins of these side walls. As the mechanisms move in closer, the springs of these elements are put under compression and the box walls are held tightly against the block. At the same time or concurrently with this holding or retaining action, the solvent applicator units are effective for engaging their applicator faces along the margins of the ends of the boxes and a controlled and measured amount of solvent is applied along the margins for subsequent attachment of the attaching flaps of the box.

For an understanding of the mechanisms which act upon the other side walls of the box, reference may be had to Figures 69 to 77 inclusive. Insofar as the slidable mounting and general support of these mechanisms are concerned, they are the same as the mechanisms just described, 35 that is, they consist of horizontally reciprocating main slide elements supported in the rectangular plate 372. Likewise, the adjustments are the same. The members 455 which are horizontally adjustable in the main slide consist, in each case, 40 of a vertically suspended element having a dovetail connection, of the type described before, in its upper end and having a cross bar or rail 456 attached to its lower end. This bar extends, in each case, longitudinally of the machine and along the side of the central block. Attachment 45 of the element 455 to the bar 456 is by means of screws 457 traversing lugs 458 extending integrally with and laterally of the element 455 and at the sides thereof. The bar lies in a cross 50 groove (Figure 70) in the inner side of the element 455 and the screws are threaded into it.

The units directly effective on the walls of the box are generally indicated at 459. In order to adjustably fasten these units upon the ends of the bars, a clamping member 460 (Figure 75) is provided in each instance in combination with the body 461 of the unit. The adjacent faces of the clamping bar and the unit are similarly grooved to fit around the bar and a pair of screws 462 pass through the upper and lower ends of the bar into the body above and below the bar 456. Thus, by means of these screws the units may be adjusted along the bar depending upon the width of the box being formed. Similarly to the mechanisms which act on the other side walls, the present mechanisms include depressible holding bars generally indicated at 463 (Figure 76). These holding bars are vertically disposed and are adapted to engage the vertical end margins of the side walls which carry the sealing flaps 275. Each of the units 459 carries one of these holding or presser bars 463. Each bar 463 is carried on a pair of slidably mounted studs 464 traversing the elements 460 and 461 of the unit. Coil springs 465 are disposed about the studs ad-

ja cent the bar, being under compression between the bar and sockets formed by counterboring the bores which slidably contain the studs. For the purpose of limiting movement of the contact bars toward the central block collars 466 are pinned to the outer projected ends of the studs.

Each of the units 459 adjacent the holding bars includes sealing flap turning and pressing elements generally indicated at 470. These elements 470 are elongated and are vertically disposed in parallelism with the contact bars 463. They are rockably mounted on the elements 461. Each element 461 includes upper and lower projected lugs 471 and the upper and lower ends of the rockable sealing flap turning elements are 15 bifurcated at 472 so as to engage over the lugs. Pivot pins 473 traverse the respective lugs and the bifurcated portions of the elements 470.

Each element 470 is held in stabilized or position of rest by means of a coil spring 474 extended between a pin 475 on the top of the element 461 and a pin 476 projecting from the rear of the element 470 (Figure 77). Normally, these elements lie in a position where they will be rotated by contact with the side wall of the box after it has been clamped in position by the bars 463. To bring about actuation and the pressing action of these elements 470 their faces are notched longitudinally vertically as at 477. This notch provides two faces 478 and 479, the first of which is the actuating face which engages the side wall along its end margin and the second of which 479 swings around the corner of the box and presses the sealing flap against the solvent coated margin of the adjoining side wall.

In order to clear the solvent applicator elements from the end margin of the adjoining wall in each instance, prior to the turning of the flap, a roller 480 (Figure 77) is mounted on a vertical stud 481 in the element 461 and projects laterally therefrom. This roller engages the element 458 described in connection with the applicator mechanism and slides the applicator mechanism away from the wall of the box (Figures 52, 53, 55 and 57) as the flap turning element comes into engagement with the flap.

For a clear understanding of the action at the respective corners of the box, reference may be had to Figures 51 to 57, inclusive, these figures depicting the sequence of operation. Figures 51 and 52 show the laterally disposed walls held in position by the bars 407 and show the applicator units applying solvent along the vertical end margins of these side walls. The flap turning mechanism is clear and has not yet started inward in its final wall forming movement. In Figure 53 the flap turning mechanism has moved in part way and the roller thereof has moved the solvent applicator outwardly through its cam element 450. In Figures 54 and 55, the flap turning mechanism has come into engagement with the side walls, the clamping bars 463 thereof have engaged and clamped the side walls and the flap turning elements 470 are just beginning to turn the flaps. In Figures 56 and 57 the flap turning elements have completed their operation and the sealing flaps are pressed against the solvent coated margins of the adjoining side walls. The faces of the flap turning devices include rubber facing elements providing for a better grip on the walls of the box.

Box discharge mechanism

After the box has been completed through the mechanisms just described, appropriate mecha-

nism is provided for removing the box from the forming block and discharging it from the machine. This mechanism is illustrated in Figures 58 to 62, inclusive. At each corner of the block and within the corner units there are mounted spreader fingers 485. These fingers are pivoted within recesses 486 in the bottoms of the corner sections on pivot pins 487. The finger portions 488 normally lie within grooves 489 in the sides of the corner elements. Depressible plungers 490 are mounted in bores 491 against coil springs 492 normally under compression. The outer ends of these plungers include small pin extensions 493 engaging the backs of the fingers tending normally to displace the fingers to the position shown in Figure 61, which is the position as the box is first brought upwardly to final forming position and after the box is released. The lower ends of the fingers include extensions 493 adapted to engage stop pins 494 fixed in angular bores in the corner members.

The purpose of the fingers 485 will be evident from a study of Figures 51 to 57, inclusive. As the box is brought upwardly on the elevating plates to dispose the bottom of the box against the under side of the forming block, it is necessary that the laterally disposed side walls or those side walls having the sealing flaps as parts thereof, be held outwardly approximately at the angle at which they are formed at the fourth station. This keeps each laterally disposed side wall at an angle where it is clear of the solvent applying and clamping mechanisms which act upon the other side walls, that is the side walls which are disposed crosswise of the machine. These fingers 485 are visible in Figures 52 and 53, being immediately adjacent the presser bars of the mechanisms which bring the sealing flaps into final positions. The weight of the fingers 485 lying in the positions indicated in Figure 61 is sufficient to keep these laterally disposed side walls at the proper angles for clearance purposes as described. As the walls are moved into final or erect position perpendicular to the bottom of the box, the fingers move easily into recessed position in the receiving grooves of the block.

Additionally, in each of the corner elements, vertical bores 496 having closed upper ends, are included. Within these bores are mounted box discharging plungers 497. These plungers include heads 498 and their main portions extend downwardly through small bores 499 at the base of the corner elements where they engage the upper side of the bottom of the box when completed. Coil springs 500 are disposed between the heads of these plungers and the bottom of the main bores. These springs are normally relaxed. Conduits 501 for air enter the sides of the corner elements and are connected through bores 502 with the upper ends of the bores 496 above the heads of the plungers 497.

After each box has been fully completed the elevating mechanism starts to lower. Thereupon, and after the holding devices are retracted, air is admitted under pressure through the conduits 501 by means of valve mechanisms synchronized with the box forming mechanisms. The air under pressure is effective for moving the plungers downwardly (Figure 59) and causing their lower ends to push the box downwardly. At the same time during which the plungers are moving the box downwardly, a certain amount of air leaks through the bores containing the pins or plungers 497 and this air aids in breaking any vacuum which might exist around the inside of the box.

because of a close fit about the forming block. This tendency for the box to cling to the forming block might tend to hold the box back and the suckers of the carrier elements might then be pulled loose from the box.

Accordingly, the box will then be drawn down by its respective carrier element until the carrier element is again connected to the conveyor chain. At this time, the box will be resting upon a pair of longitudinally disposed rails 582 fixed along the top of the elevating plates 212 for this particular station (Figure 58). These rails are adjustable laterally in the plates, so as to be directly beneath the plungers 467, the plates including lateral slots for this purpose, traversed by screws (Figure 1). These rails support the box against bending as the discharge pins 457 press downwardly on the bottom of the box. The tops of these guide rails are in the same plane as the tops of the suction cups when the elevating plates and carrier elements are up. When the elevating plates and carrier elements are down, the guides or supporting rails have their upper surfaces disposed just below the plane of the suction cups so that the boxes do not rub on these guide elements as the chain moves to discharge them from the machine. When the chain is again indexed or moved, the carrier elements as they pass around the driven sprocket, pass through the clearance slot 593 of a discharge chute 584. This plate is fixed in the frame of the machine at an angle as shown in Figure 1. Its upper end is disposed below the plane of the bottom of the box and extends into the machine to a point adjacent the ends of the elevating plates. Therefore, as the carrier elements swing around the end of the chain loop, the bottoms of the boxes engage the top of the chute and the boxes are stripped off the suction cups and slide down the chute for final discharge from the machine.

The entire machine is driven by means of a motor 585, the motor including a worm gear 586 meshing with a worm wheel 587 fixed to the drive shaft 152 adjacent the fifth station.

General description of operation

In order to make clear the synchronization of the machine, a chart or graph has been illustrated in Figure 89. This chart along its upper edge shows the degrees of a complete rotation of the drive shaft which represents one cycle and the production of one box in the operation of the machine. Within this cycle, five operations are performed as described in the beginning of the description. In other words, five separate boxes in various stages of completion are acted upon in each cycle.

It will be noted that the operations at the five stations indicated on the chart as "pick-up" at the first station, "stamp" at the second station, "crimp" at the third station, "crimp" at the fourth station, and both "solvent" and "seal" at the fifth station occur within the same general zone of degrees in the cycle. The operation of sealing as indicated occurs at the end of the solvent application operation. The pick-up or elevating operation applies to all stations. In other words, the five elevating mechanisms all operate simultaneously. The elevating mechanism at the first station is referred to as "pick-up" for the only function at this station is for the elevating mechanism to rise up and engage the blank just prior to the cut-off operation. As shown on the chart, the cut-off operation occurs while the elevating mechanism has paused at the top of its

stroke. In other words, the end section of the roll of plastic is being held tightly against the contact arm 251 while the cut-off knife is severing the section from the roll.

As will be evident at the top of the chart, the feed mechanism which is the second line on the graph is operating for the "return" or idle motion throughout the time that the "cut-off" and "pick-up" is taking place. After the elevating mechanism at the first station is lowered, the feed motion is then applied to feed another section of the roll into position in the first station, this taking place when all of the mechanisms with the exception of the carrier transporting mechanism are stationary. Just as the feed motion starts and all of the elevating mechanisms are down and the carriers engaged with the chain blocks 227, an indexing motion is imparted to the chain to move all carriers to the next station, and to bring up an empty carrier to the first station. The return or idle motion of the chain occurs, as indicated, while all of the various operations are taking place at the different stations. An inspection of the chart in the light of the above description will make clear the synchronization of the various mechanisms for a given cycle.

In order to make clear the operations performed to make up a box from the continuous roll to the finished box, a general description of the operation of the machine is set forth. The sheet of plastic is contained in the roll 100 and is mounted on the reel 101 at the intake end of the machine. From the roll, the sheet is fed between the feed rollers 123, 124 and from there between the shears 177, 178 of the cut-off mechanism. As each intermittent feed motion is effective an end section of the plastic will be fed between the contact arm 251 and the elevating mechanism at the first station. This motion will deliver a length of the plastic sufficient to make up one square box, the amount of feed corresponding exactly to the width of the sheet as delivered from the roll except in the case of rectangular boxes.

When the feeding mechanism pauses at the end of its delivery stroke, the center of the square section of material will lie directly in alignment with the axis of the carrier to which it is to be attached. The suckers on the carrier will be pressed against the underside of the plastic and the plastic will be gripped between the contact arm 251 and the suckers. At this time, as will be evident from the chart, the endmost section is cut off. Thereupon, the elevating mechanism is lowered through its cam 239 and the stud of the carrier will be engaged into the socket of the carrier block 227 on the chain. The detents 235 in the block will assure absolute alignment of the parts so that the blank will be squared up with the machine for future operations. As soon as the carrier is securely attached to its block, motion is imparted to the chain to move it the exact distance between stations, thus bringing the particular carrier up to the second or the station at which the corners are cut out.

The cam 239 at this station will then be effective for elevating the elevating plates 212 of the particular station and the carrier will be lifted from its socket and moved up to dispose the blank against the upper or male dies 266. The blank, as fed along the machine, is disposed between the male and female dies 266, 267 and the action of the elevating plates is to first move the lower or female dies 267 upwardly until they are in contact with the blank at

33

which time the carrier itself is being elevated. Thus, when the blank comes into contact with the male dies, the female dies will be just beneath the plastic and the trimming operation will take place with the blank properly supported. Following the trimming motion and as the elevating plates are lowered, the depressible elements 278 in the female dies will move up to clear the trimmings from the confines of the dies following which air delivered through the air nozzles 282 will blow the trimmings clear of the machine.

The elevating mechanism then lowers to again connect the carrier to its companion block on the chain and another movement of the chain will take place to transport the carrier to the next station. This station is the third or primary wall forming station and the operation here is effective for again raising the carrier and co-incident therewith raising the lower die elements 301 of this station to crimp the material against the upper dies 300 and to form up the side walls at the angles controlled by the angular sides of the upper dies. This same operation is effective for forming the sealing flaps 275 since the end margins of the other side walls extend beyond the lines of the crimping operations. As stated, the material may be heated at this point to make it more plastic and to cause it to maintain its set crimped condition.

Following the above operation, the elevating mechanism is lowered, lowering the carrier back into its companion carrier block on the chain. As the carrier moves from this station to the next, the carrier through its pins 221 will engage the stationary indexing cam block 320 and the blank will be rotated through a ninety degree arc, thus disposing the previously crimped side walls in positions crosswise of the machine and disposing the other margins of the bottom in position to be crimped up into the remaining side walls.

The operation at the fourth station is the same as that at the third station. The walls now formed up at this station include the sealing flaps, the lines of fold of these sealing flaps being crimped at the last station. As in the preceding station, the carrier is again lowered into engagement with its companion block and further movement of the chain carries the box to the final or fifth station.

As the box is brought into this final station, it now has a bottom 306 and four sides 313, 317 with sealing flaps 275 at each end of those sides which are disposed laterally of the machine. At the fifth station, the elevating mechanism again picks up the carrier and this time nests it upon the forming block, that is to say the bottom 306 is brought up against the forming block and the four loosely formed sides surround the block. The cam gear 377 at this station, through its track, causes a simultaneous inward movement of the holding and solvent applying mechanisms adjacent the sides which are disposed crosswise of the machine. As these mechanisms slide inwardly their first action is to grip and hold the sides tightly against the sides of the block following which the solvent is applied along the vertical end margins of the sides close to the ends.

Further movement of the cam gear through its cam track, slides in the mechanisms 459 at the other sides of the box. As these mechanisms move in the solvent applying units 413 are moved clear of the sealing flaps 275. The presser bars

34

of these mechanisms 459 force the sides against the sides of the block and grip them there while the sealing flaps are turned around the corners and pressed against the solvent coated vertical margins of the adjacent sides. Before the elevating mechanism starts down, these mechanisms acting on all four sides, are moved away from the block.

Thereupon, the elevating mechanism descends and after it is clear of the box, the box is blown from the block by means of a blast of air delivered through the block against the plungers 497 which mechanically engage the bottom of the box. The action of these plungers is fast enough to shove the box quickly so as to discharge it or cause it to be forced from the block. The finished box is then moved down to the chain and the retracted carrier then re-engages its companion block. As the carrier element moves on, the box is stripped off on the discharge chute and the carrier element moves around the bottom of the chain finally coming up again at the first station for a further cycle of operations. In other words, the carrier blocks at the top of the chain are active and those on the bottom are being returned for subsequent use. Thus, it will be obvious that the machine in handling the plastic material has operated on the material without scratching it. Wherever possible, rubber facings are used. The movement of the blank by the chain as it progresses through the machine does not drag the material at any point. The result, therefore, is a clear plastic box with the material in the same fully transparent condition as when it entered the machine.

The blanks or boxes, as they pass through the machine, are not scratched or marred since the carrier elements hold the blanks or boxes approximately a half inch above the surface of the various dies or elements so that while the carrier elements are being moved or indexed the only support of the blanks is on the rubber cups and they therefore rub on nothing. After the blanks or boxes stop moving, the elevating mechanisms move up to bring the die elements upwardly against the blank. Thus, the surface of the plastic material is protected during all functions of the machine.

Having described our invention, we claim:

1. In a box making machine of the type forming rectangular boxes by crimping and folding sheet plastic blanks; a conveyor mechanism consisting of an endless loop of chain, sprocket gears supporting said loop of chain, means for driving one of said gears, said chain having carrier blocks mounted thereon, these blocks being disposed at equally spaced intervals on the chain, carrier elements mounted in said blocks, said blocks including sockets and said carrier elements including studs rotatively engaged in said sockets, detent means in the sockets for holding the carrier elements against accidental rotation, said carrier elements including detent notches spaced 90° apart around the stud, said carrier elements including sucker elements adapted to engage and support said blanks for transporting said blanks through the machine, a cam element having a channel shaped track for rotating said carrier elements, said cam element being mounted adjacent the path of movement of the chain, and pins on the carrier elements adapted to be confined within the channel shaped cam track as the chain moves past said cam, said cam track constructed and arranged so as to rotate the carrier elements 90°

as each carrier element passes said cam, whereby the sheet plastic blanks are rotated 90° with no contact with the machine other than the sucker elements.

2. In a box making machine of the type forming rectangular boxes by crimping and folding sheet plastic blanks, a conveyor mechanism consisting of an endless loop of chain, sprocket gears supporting said loop of chain, means for driving one of said gears, said chain having carrier blocks mounted thereon, these blocks being disposed at equally spaced intervals on the chain, carrier elements mounted in said blocks, said blocks including sockets and said carrier elements including studs rotatively engaged in said sockets, detent means in the sockets for holding the carrier elements against accidental rotation, said carrier elements including detent notches spaced 90° apart around the stud, said carrier elements including suckers adapted to engage and support said blanks for transporting said blanks through the machine, and stationary cam means for rotating the carrier elements 90° as they are moved along on the chain.

3. In a box making machine of the type forming rectangular boxes by crimping and folding sheet plastic blanks; mechanism for transporting the blanks through the machine for the various operations consisting of, a conveyor chain of endless loop form, sprocket gears supporting the loop of chain at its respective ends, means for driving one of said sprocket gears, a guide rail for guiding and supporting the upper run of the chain, a series of carrier blocks fixed to the chain at spaced points thereon, said carrier blocks including sockets having detents therein, carrier elements including studs adapted to be removably engaged in said sockets, the machine having mechanism constructed and arranged to elevate and replace the said carrier elements upon said carrier blocks for the various forming operations, said studs having detent recesses for indexing the studs at positions 90° apart, and said carrier elements being provided with sucker cups adapted to contact and grip the sheet plastic blanks centrally thereof, whereby the only contact with the blanks in the transportation is the engagement of the suction cups therewith.

4. In a box making machine of the type forming rectangular boxes by crimping and folding sheet plastic blanks; mechanism for transporting the blanks through the machine for the various operations consisting of, a conveyor chain of endless loop form, sprocket gears supporting the loop of chain at its respective ends, means for driving one of said gears, a guide rail for guiding and supporting the upper run of the endless chain, a series of carrier blocks fixed to the chain at spaced points thereon, said carrier blocks including sockets, carrier elements including studs adapted to be removably engaged in said sockets, the machine being constructed and arranged to elevate and replace the said carrier elements upon said carrier blocks for the various forming operations, and said carrier elements being provided with sucker cups adapted to contact and grip the sheet plastic blanks centrally thereof, whereby the only contact with the blanks in the transportation is the engagement of the suction cups therewith.

5. In a box making machine of the type forming rectangular boxes by crimping and folding sheet plastic blanks; mechanism for transporting the blanks through the machine for the var-

ious operations consisting of a conveyor chain of endless loop form, sprocket gears supporting the loop of chain at its respective ends, means for driving one of said gears, a guide rail for guiding and supporting the upper run of the endless chain, a series of carrier blocks fixed to the chain at spaced points thereon, said carrier blocks including sockets, carrier elements including studs adapted to be removably engaged in said sockets, the machine being constructed and arranged to elevate and replace the carrier elements upon said carrier blocks for the various forming operations and said carrier elements being provided with means adapted to grip the plastic sheet blanks for supporting the blanks for movement through the machine.

6. In a box making machine of the type forming rectangular boxes by crimping and folding sheet plastic blanks; a conveyor mechanism consisting of an endless loop of chain providing parallel upper and lower runs, sprocket gears for mounting respective ends of the loop of chain, a guide channel element for guiding the upper run of chain, carrier blocks fixed to the chain at intervals thereon, said carrier blocks including sockets having detents therein, carrier elements having studs removably engaged in said sockets and including detent depressions located 90° apart, means for rotating one of the sprocket gears to move the chain intermittently a distance equal to the spacing of the carrier blocks, sucker means on the carrier elements for gripping and holding said plastic sheet blanks thereon in positions parallel with the path of movement of the chain, a cam element including a channel shaped cam track, said cam element mounted relative to the guide channel element between those points on the guide channel element at which the carrier blocks pause, cam pins on the carrier elements adapted to be confined in the channel shaped cam track as the carrier elements are transported past the cam element for causing rotation of the carrier elements through 90° arcs, thus rotating the blanks so as to dispose their previously arranged cross edges in positions parallel with the path of travel of the chain.

7. In a box making machine of the type forming rectangular boxes by crimping and folding sheet plastic blanks; a conveyor mechanism consisting of an endless loop of chain providing parallel upper and lower runs, sprocket gears for mounting respective ends of the loop of chain, a guide channel element for guiding the upper run of chain, carrier blocks fixed to the chain at intervals thereon, said carrier blocks including sockets, carrier elements having studs removably and rotatably engaged in said sockets, means for rotating one of the sprocket gears to move the chain intermittently a distance equal to the spacing of the carrier blocks, sucker means on the carrier elements for gripping and holding said plastic sheet blanks thereon in positions parallel with the path of movement of said chain, a cam element including a cam track, said element mounted relative to the guide channel element between those points on the guide channel element at which the carrier blocks pause, cam pins on the carrier elements adapted to engage in the cam track as the carrier elements are transported past the cam element for causing rotation of the carrier elements through 90° arcs, thus rotating the blanks so as to dispose their previously arranged cross edges in

positions parallel with the path of travel of the chain.

8. In a box making machine of the type forming rectangular boxes by crimping and folding sheet plastic blanks; a conveyor mechanism consisting of an endless loop of chain providing parallel upper and lower runs, sprocket gears for mounting respective ends of the loop of chain, a guide channel element for guiding the upper run of chain, carrier blocks fixed to the chain at intervals thereon, said carrier blocks including sockets, carrier elements having studs rotatively and removably engaged in said sockets, means for rotating one of the sprocket gears to move the chain intermittently a distance equal to the spacing of the carrier blocks, means on the carrier elements for gripping and holding said plastic sheet blanks thereon in positions parallel with the path of travel of said chain, means for rotating said carrier elements through 90° arcs as the carrier elements are transported by the chain, thus rotating the blanks so as to dispose their previously arranged cross edges in positions parallel with the path of travel of the chain, the machine being constructed and arranged to elevate and replace the carrier elements with respect to said carrier blocks for the various box forming operations as the carriers are conveyed through the machine.

9. In a box making machine of the type forming rectangular boxes by crimping and folding sheet plastic blanks; a conveyor mechanism, means for intermittently translating said mechanism, carrier elements disconnectably mounted on said conveyor mechanism, said carrier elements including suction means for engaging and gripping said sheet plastic blanks, translatable means for engaging and moving said carrier elements away from said conveyor mechanism as the carrier elements pause between intermittent motions, and forming mechanism engaging and forming the blanks while engaged by said translatable means.

10. In a box making machine of the type forming rectangular boxes by crimping and folding sheet plastic blanks; an endless conveyor chain, sprocket gears for supporting the respective ends of the chain, means for intermittently rotating one of said gears, a series of carrier elements vertically removable mounted on the chain at intervals thereon equal to the length of the intermittent motion, successive crimping and wall forming mechanisms located adjacent the conveyor chain and spaced apart an amount equal to the length of the intermittent movement of the chain, each of said carrier elements including sucker elements for gripping and holding said blanks in position for transportation parallel with the plane of said blanks, and translating mechanism adjacent each crimping and wall forming mechanism for urging said vertically movable carrier elements and blanks as a unit at right angles to the plane of the blanks against said mechanisms for forming the side walls of the box.

11. In a box making machine of the type forming rectangular boxes by crimping and folding sheet plastic blanks; an endless conveyor chain, sprocket gears for supporting the respective ends of the chain, means for intermittently rotating one of said gears, a series of carrier elements disconnectably mounted on the chain at intervals thereon equal to the length of the intermittent motion, successive crimping and wall forming mechanisms located adjacent the conveyor chain

and spaced apart an amount equal to the length of the intermittent movement of the chain, each of said carrier elements including sucker elements for gripping and holding said blanks, and translating mechanisms adjacent each crimping and wall forming mechanism for moving the carrier elements and blanks as a unit from and to engagement with the chain to cause the blanks to engage the respective crimping and wall forming mechanisms.

12. In a box making machine of the type forming rectangular boxes by crimping and folding sheet plastic blanks; an endless conveyor chain, sprocket gears for supporting the respective ends of the chain, means for intermittently rotating one of said gears, a series of carrier elements disconnectably and rotatively mounted on the chain at intervals thereon equal to the length of the intermittent motion, successive crimping and wall forming mechanisms consisting of spaced parallel die elements located adjacent the conveyor chain and spaced apart an amount equal to the length of the intermittent movement of the chain, each of said carrier elements including sucker elements for gripping and holding said blanks in position for transportation parallel with the plane of said blanks, translating mechanism adjacent each crimping and wall forming mechanism for urging the disconnectable carrier elements and blanks as a unit in directions perpendicular to blanks against said mechanisms for forming pairs of side walls, and means between said crimping and wall forming mechanisms for rotating the blanks 90° whereby, the blanks are formed to provide the four walls of a rectangular container.

13. In a box making machine of the type forming rectangular boxes by crimping and folding sheet plastic blanks; an endless conveyor chain, sprocket gears for supporting the respective ends of the chain, means for intermittently rotating one of said gears, a series of carrier elements disconnectably mounted on the chain at intervals thereon equal to the length of the intermittent motion, a crimping and wall forming mechanism located adjacent the conveyor chain, the said intermittent rotation of the gear being such that the carrier elements are successively advanced to operating positions with respect to the gripping and wall forming mechanism, each of said carrier elements including means for gripping and holding said blanks, translating mechanism adjacent the crimping and wall forming mechanism for moving said carrier elements out of connection with the chain and the blanks against said mechanism for forming side walls on the blank.

14. In a box making machine of the type forming rectangular boxes by crimping and folding sheet plastic blanks; a conveyor chain mechanism of endless loop form, gears for supporting the respective ends thereof, means for intermittently driving one of said gears, carrier elements disconnectably and rotatably mounted on said conveyor chain, a first crimping and wall forming mechanism located adjacent the chain at a point where the carrier elements successively pause, a second crimping and wall forming mechanism located adjacent the chain at the next position of pause of the carrier elements, said crimping and wall forming mechanisms consisting of spaced parallel vertically disposed forming dies, disposed parallel to the path of movement of the chain and having upwardly outwardly inclined outer surfaces and lower rounded crimping edges, means

on the carrier elements for supporting and carrying said blanks in position parallel with the path of movement of the chain and at right angles to the dies, means for moving the carrier elements away from the chain and the blanks against said crimping edges, and means along the chain interposed between the crimping and wall forming mechanisms for indexing the carrier elements through 90° so that the respective crimping and wall forming mechanisms set up walls at right angles to each other to form a rectangular box, the walls being slightly inclined outwardly from their finished positions.

15. In a box making machine of the type forming rectangular boxes by crimping and folding sheet plastic blanks; a conveyor chain mechanism of endless loop form, gears for supporting the respective ends thereof, means for intermittently driving one of said gears, carrier elements disconnectably mounted on said conveyor chain, a crimping and wall forming mechanism located adjacent the chain at that point where the carrier elements are adapted to pause, said crimping and wall forming mechanism consisting of spaced die plates which are disposed along and parallel with the path of movement of the chain and which have upwardly outwardly inclined outer surfaces and lower rounded crimping edges, and means on the carrier elements for supporting and carrying said blanks parallel with the path of movement of the chain, and means for moving said carrier elements away from the chain and the blanks against said crimping edges so that the crimping and wall forming mechanisms set up the opposite walls of the box, which walls are slightly inclined outwardly from their finished positions.

16. In a box making machine of the type forming rectangular boxes by crimping and folding sheet plastic blanks; a conveyor chain mechanism of endless loop form, gears for supporting the respective ends thereof, means for intermittently driving one of said gears, carrier elements for transporting said blanks, the said carrier elements being removably mounted on said conveyor chain, a first set of crimping and wall forming dies located adjacent the chain at that point at which the carrier elements are adapted to pause, a second set of crimping and wall forming dies located adjacent the chain at the next position of pause of the carrier elements, and means cooperating with said conveyor chain and carrier elements for removing the carrier elements and blanks as a unit and engaging said blanks against said dies.

17. In a box making machine of the type forming rectangular boxes by crimping and folding sheet plastic blanks; a conveyor chain of endless loop form, sprocket gears mounting the respective ends of said endless chain, a series of carrier blocks mounted on said chain at equally spaced points thereof, carrier elements rotatively and disconnectably associated with said blocks and having means thereon for gripping and holding said blanks, said blanks being disposed for travel in a plane parallel to their top and bottom surfaces, means for delivering blanks to positions to be successively engaged on said carrier elements, a side wall crimping and folding mechanism located adjacent said chain, means for intermittently driving one of said sprocket gears for moving the carrier blocks intermittently a distance equal to their spacing on the chain, said crimping and folding mechanism being located adjacent the chain at a point where the successive carrier elements pause, means for disconnecting the car-

rier elements from the carrier blocks and moving the same with the blanks gripped thereon as a unit and engaging the blanks successively against the crimping and folding mechanism, a second wall crimping and folding mechanism spaced from the first-named crimping and folding mechanism a distance equal to that between carrier blocks, means adjacent the chain between the respective wall crimping and folding mechanisms for rotating the carrier elements 90°, and mechanism for urging the carrier blanks successively against the second crimping and folding mechanism to produce walls at right angles to those first formed.

15. In a box making machine of the type forming rectangular boxes by crimping and folding sheet plastic blanks; a conveyor chain of endless loop form, sprocket gears mounting the respective ends of said endless chain, a series of carrier blocks on said chain at equally spaced points thereon, carrier elements disconnectably mounted on said blocks and having suction means thereon for gripping and holding said blanks by contact with the sides thereof, said blanks being disposed for travel in a plane parallel to their top and bottom surfaces, means for delivering said blanks to positions to be successively engaged on the carrier elements, a side wall crimping and forming mechanism located adjacent said chain, means for intermittently driving one of said sprocket gears for moving the carrier blocks intermittently a distance equal to their spacing on the chain, said crimping and forming mechanism being located adjacent the chain at a point where the successive carrier elements pause, and means for disconnecting the carrier elements from the carrier blocks and moving the same with the blanks gripped thereon as a unit and engaging the blanks successively against the crimping and forming mechanism.

19. In a box making machine of the type forming rectangular boxes by crimping and folding sheet plastic blanks; conveyor means, carrier elements rotatively and disconnectably mounted on said conveyor means and having means thereon for gripping and holding said blanks, means for delivering said blanks to positions to be successively engaged on said carrier elements, a side wall crimping and forming mechanism located adjacent said conveyor means, means for intermittently translating said conveyor means for moving the carrier blocks intermittently the distance equal to their spacing on the conveyor means, said crimping and wall forming mechanism being located adjacent the conveyor means at a point where the successive carrier elements pause, means for engaging the blanks successively against the crimping and forming mechanism, a second wall crimping and forming mechanism spaced from the first-named crimping and forming station the distance equal to that between carrier blocks, and means adjacent the conveyor means between the respective crimping and forming mechanisms for rotating the carrier elements 90°, and mechanism for disconnecting the carrier elements from the conveyor means and moving the carrier with the blanks gripped thereon successively against the second crimping and forming mechanism to produce walls at right angles to those first formed.

20. In a box making machine of the type forming rectangular boxes by crimping and folding sheet plastic blanks; a conveyor chain of endless loop form, sprocket gears for mounting the respective ends of the chain, means for driving

one of said sprocket gears intermittently, carrier elements disconnectably mounted on said chain at spaced intervals, said carrier elements including gripping elements thereon for supporting the blanks for transportation by the chain, trimming dies mounted adjacent the chain at a point at which the carrier elements successively pause, wall forming dies disposed adjacent the next position of pause of the carrier elements and translating mechanisms moving in directions at right angles to the path of movement of the chain and adapted to engage the carrier elements and to disconnect the same from the chain for moving them away from the chain and into contact with the respective die mechanisms and for returning them to connection with the chain.

21. In a box making machine of the type forming rectangular boxes by crimping and folding sheet plastic blanks; a conveyor means, means for driving said conveyor means intermittently, carrier elements disconnectably mounted on said conveyor means at spaced intervals, said carrier elements including suction elements thereon for supporting said blanks for transportation by the conveyor means, trimming dies mounted adjacent the conveyor means at a point at which the carrier elements successively pause, wall forming dies disposed adjacent the next position of pause of the carrier elements and translating mechanisms moving in directions at right angles to the path of movement of the conveyor means and adapted to engage the carrier elements and to disconnect the same from the chain for moving them away from the conveyor means and into contact with the respective die mechanisms and for returning them to connection with the conveyor means.

22. In a box making machine of the type forming rectangular boxes by crimping and folding sheet plastic blanks; a conveyor mechanism, means for supporting said blanks on the conveyor mechanism at spaced points thereon, said latter means being disconnectable from the conveyor mechanism, wall forming mechanisms located adjacent said conveyor mechanism, means for moving the blank supporting means away from and out of connection with the chain, suction elements provided on said blank carrying means for supporting the blanks thereon, said conveyor mechanism adapted to pause at each wall forming mechanism and said blank supporting means being adapted to be disconnected from the conveyor and moved with the blank thereon against the wall forming mechanisms for setting up opposite walls of the box in each instance, a forming block located adjacent the conveyor mechanism at the next position of pause beyond the wall forming mechanisms, slide mechanisms located around the forming block for pressing the sides of the blank against the block, said sides including cooperating sealing flaps and, mechanism associated with the slides for adhesively securing the flaps in positions for completing the box.

23. In a box making machine of the type forming rectangular boxes by crimping and folding sheet plastic blanks; a conveyor mechanism, means for supporting said blanks on the conveyor mechanism at spaced points thereon, said latter means being disconnectable from the conveyor mechanism, wall forming mechanisms located adjacent said conveyor mechanism, means for moving the blank supporting means away from and out of connection with the chain, suction elements provided on said blank carrying means

for supporting the blanks thereon, said conveyor mechanism adapted to pause at each wall forming mechanism and said blank supporting means being adapted to be disconnected from the conveyor and moved with the blank thereon against the wall forming mechanisms for setting up the opposite walls of the box in each instance, a forming block located adjacent the conveyor mechanism at the next position of pause beyond the wall forming mechanisms, and wall engaging mechanisms located around the forming block for pressing the sides of the blank against the block and into finished squared relationship.

24. Apparatus for applying solvent to the end margins of the side walls of box blanks for attachment of sealing flaps of the other sides of the box to said end margins, comprising; solvent applicators which include elongated members adapted to engage the vertical end margins of opposite side walls of the box blank, said members having projected contact faces, means for delivering the solvent to said contact faces under controlled pressure, and suction means for drawing off the excess solvent from said contact faces.

25. Apparatus for applying solvent to the end margins of the side walls of box blanks for attachment of the sealing flaps of the other sides to said end margins, comprising; slidably mounted solvent applicators which include elongated members adapted to engage the vertical end margins of opposite side walls of the box blank, said members having projected contact faces constituted of minute spherical elements bonded together but sufficiently porous to permit seepage of solvent to the faces, means for delivering the solvent to said contact faces under controlled pressure, and suction means for drawing off the excess solvent from said contact faces, said latter means being connected to the lower end of the faces where the solvent collects by gravity.

26. Apparatus for applying solvent to the end margins of the side walls of box blanks for attachment of the sealing flaps of the other side walls to said end margins, comprising; solvent applicators which include elongated members adapted to engage the vertical end margins of opposite side walls of the box blank, said members having projected contact faces, means for delivering the solvent to said contact faces under controlled pressure, and suction means for drawing off the excess solvent from said contact faces, said latter means being connected to the lower end of the faces where the solvent collects by gravity.

27. In a box making machine of the type adapted to produce rectangular boxes by crimping and folding sheet plastic blanks; apparatus for applying plastic dissolving solvent to the end margins of the side walls of box blanks to form an adhesive film upon the said end margins for securing the same, comprising, a rectangular forming block adapted to be embraced by the partly formed box, means for holding the side walls of the box against the side walls of said block, slidably mounted solvent applicators which include elongated contact members adapted to engage the vertical end margins of opposite side walls of the box blank for attachment of the sealing flaps on the other sides of the box to said end margins and means for delivering the solvent to said contact members.

28. In a box making machine of the type adapted to produce rectangular boxes by crimping and folding sheet plastic blanks; apparatus for applying solvent to the end margins of the side

walls of box blanks; comprising, a rectangular forming block adapted to be embraced by the partly formed box, means for holding the side walls of the box against the side walls of said block, slidably mounted solvent applicators which include elongated contact members adapted to engage the vertical end margins of opposite side walls of the box blank for attachment of sealing flaps of the other sides to said end margins, means for delivering the solvent to said contact members under controlled pressure, and suction means for drawing off the excess solvent from said contact members, said latter means being connected to the lower end of the members where the solvent collects by gravity.

29. In a box making machine of the type adapted to produce rectangular boxes by crimping and folding sheet plastic blanks; apparatus for applying solvent to the end margins of the side walls of box blanks for the connection of the adjacent sealing flaps of the other sides, comprising, a rectangular forming block adapted to be embraced by the partly formed box, means for holding the side walls of the box against the side walls of said block, slidably mounted solvent applicators which include elongated members adapted to engage the vertical end margins of opposite side walls of the box blank for attachment of the sealing flaps of the other sides thereto, said elongated members having projected contact faces constituted of minute spherical elements bonded together but sufficiently porous to permit seepage of solvent to the faces, means for delivering the solvent to said contact faces under controlled pressure, and suction means for drawing off the excess solvent from said contact faces, said suction means being connected to the lower end of the faces where the solvent collects by gravity.

30. In a box making machine of the type forming rectangular boxes by crimping and folding rectangular sheet plastic blanks; intermittently driven conveyor means for transporting said blanks through the machine, said conveyor means including carrier elements at spaced intervals, said carrier elements including means adapted to grip said blanks, elevating plates disposed along each side of the path of travel of the conveyor means, said carrier elements adapted to traverse the space between the plates, lower trimming die elements supported by the elevating plates and disposed beneath the corners of each plastic sheet blank as it pauses in the movement of the conveyor means, upper trimming die elements located immediately above the lower die elements and supported on the machine, and means for actuating the elevating plates to move them upwardly for bringing the upper and lower dies together and trimming the corners of the blanks.

31. In a box making machine of the type forming rectangular boxes by crimping and folding rectangular sheet plastic blanks; intermittently driven conveyor means for transporting said blanks through the machine, said conveyor means including carrier elements at spaced intervals, said carrier elements including sucker means on the tops thereof adapted to grip the undersides of said blanks, elevating plates disposed along each side of the path of travel of the conveyor means, said carrier elements adapted to traverse the space between the plates, lower trimming die elements supported by the elevating plates and disposed beneath the corners of each blank as it pauses in the movement of the conveyor means, 75

upper trimming die elements located immediately above the lower die elements and supported on the machine, said lower die elements including compressible plates therein, said plates corresponding in size to the shape of the trimming portions of the upper dies and disposed in recesses in the lower die elements, said plates being compressible in said recesses, said lower die elements guided with respect to the upper die elements for movement toward and from the upper die elements, the pairs of upper and lower die elements being adjustable toward and from each other crosswise and lengthwise of the machine, and means for actuating the elevating plates to move them upwardly for bringing the upper and lower dies together and trimming the corners of the blanks.

32. In a box making machine of the type forming rectangular boxes by crimping and folding rectangular sheet plastic blanks; intermittently driven conveyor means for transporting said blanks through the machine, said conveyor means including carrier elements at spaced intervals, said carrier elements including sucker means on the tops thereof adapted to grip the undersides of said blanks, elevating plates disposed along each side of the path of travel of the conveyor means, said carrier elements adapted to traverse the space between the plates, lower trimming die elements supported by the elevating plates and disposed beneath the corners of each blank as it pauses in the movement of the conveyor means, there being clearance between said lower dies and said blank when the elevating plates are in lower position, upper trimming die elements located immediately above the lower die elements and supported on the machine, and means for actuating the elevating plates to move them upwardly for bringing the upper and lower dies together and trimming the corners of the blanks.

33. In a box making machine of the type forming rectangular boxes by crimping and folding rectangular sheet plastic blanks; intermittently driven conveyor means for transporting said blanks through the machine, said conveyor means including carrier elements at spaced intervals, said carrier elements including sucker means on the tops thereof adapted to grip the undersides of the plastic sheet blanks, elevating plates disposed along each side of the path of travel of the conveyor means, said carrier elements adapted to traverse the space between the plates, lower trimming die elements supported by the elevating plates and disposed beneath the corners of each plastic sheet blank as it pauses in the movement of the conveyor means, upper trimming die elements located immediately above the lower die elements and supported on the machine, and means for actuating the elevating plates to move them upwardly for bringing the upper and lower dies together and trimming the corners of the blanks.

34. In a box making machine of the type forming rectangular boxes by crimping and folding rectangular sheet plastic blanks; a conveyor mechanism consisting of an endless chain of loop form having sprockets at its respective ends, means for intermittently driving one of said sprockets, carrier elements detachably mounted on said chain at spaced points and including outwardly projecting sucker elements adapted to grip and hold said blanks, carrier element elevating plates disposed along either side of the path of travel of the chain, the space therebetween being traversed by the carrier elements,

45

upper and lower die elements disposed along either side of said chain parallel therewith, the lower of said die elements supported by the plates but guided vertically with respect to the upper die elements, the upper die elements consisting of vertically disposed plates, the lower edges of which engage the lower dies for crimping the blanks, the outer walls of these plates being inclined upwardly outwardly, said suction means disposing said blanks in a horizontal plane above the plane of the lower dies and, means for elevating the elevating plates for moving the lower dies, the carrier elements, and the plastic blanks upwardly as a unit against the upper dies for causing bending of the side portions of the blank upwardly against the inclined sloping sides of the upper dies.

35. In a box making machine of the type forming rectangular boxes by crimping and folding rectangular sheet plastic blanks; a conveyor mechanism, means for intermittently driving said conveyor mechanism, carrier elements detachably mounted on said mechanism at spaced points and including outwardly projecting sucker elements adapted to grip and hold said blanks, carrier element elevating plates disposed along either side of the path of travel of the conveyor mechanism, the space therebetween being traversed by the carrier elements, upper and lower die elements disposed along either side of the conveyor mechanism parallel therewith, the lower of said die elements supported by the plates but guided vertically with respect to the upper die elements, said carrier elements supporting said blanks between said dies, and means for actuating said elevating plates for actuating said dies and forming side walls on said blanks.

36. In a box making machine of the type forming rectangular boxes by crimping and folding rectangular sheet plastic blanks; a conveyor mechanism consisting of an endless chain of loop form having sprockets at its respective ends, means for intermittently driving one of said sprockets, carrier elements detachably mounted on said chain at spaced points and including outwardly projecting sucker elements adapted to grip and hold said blanks, elevating plates disposed along either side of the path of travel of the chain for moving said carrier elements upwardly from said chain, the space therebetween being traversed by the carrier elements, upper and lower die elements disposed along either side of said chain parallel therewith, the lower of said die elements supported by the plates but guided vertically with respect to the upper die elements, and means for moving said elevating plates upwardly for moving the lower dies and the carrier elements and causing the lower die elements and the plastic blank to move as a unit against the upper dies thereby bending the side portions of the blank upwardly to form side walls.

37. In a box making machine of the type forming rectangular boxes by crimping and folding rectangular sheet plastic blanks; a conveyor mechanism consisting of an endless chain of loop form having sprockets at its respective ends, means for intermittently driving one of said sprockets, carrier elements detachably mounted on said chain at spaced points and including outwardly projecting sucker elements adapted to grip and hold said blanks, elevating plates for detaching said carrier elements from said chain in an upward direction, disposed along either side of the path of travel of the chain, the space therebetween being traversed by the carrier elements,

75

46

upper and lower die elements disposed along either side of said chain parallel therewith, the lower of said die elements supported by the plates but guided vertically with respect to the upper die elements, said sucker elements being disposed in a horizontal plane with their upper surfaces slightly above the plane of the lower dies and, means for elevating the elevating plates for moving the lower dies upwardly in the first phase of movement and then moving the carrier elements and causing the lower die elements and the plastic blank to move as a unit against the upper dies thereby bending the side portions of the blank upwardly to form opposite walls of the box.

38. In a box making machine of the type forming rectangular boxes by crimping and folding rectangular sheet plastic blanks; a conveyor mechanism consisting of an endless chain of loop form having sprockets at its respective ends, means for intermittently driving one of said sprockets, carrier elements detachably mounted on said chain at spaced points and including outwardly projecting sucker elements adapted to grip and hold said blanks, elevating plates disposed along either side of the path of travel of the chain, adapted to move said carrier elements upwardly out of connection with said chain, the space therebetween being traversed by the carrier elements, upper and lower die elements disposed along either side of said chain parallel therewith, the lower of said die elements supported by the plates but guided vertically with respect to the upper die elements, the lower die elements including minute grooves therein along their upper surfaces parallel with the path of travel of the chain, the upper die elements consisting of vertically disposed plates, the lower edges of which coincide and register with said minute grooves, the outer walls of these plates being inclined upwardly outwardly, heating means in said upper die elements, said suction means being disposed in a horizontal plane with their upper surfaces slightly above the plane of the lower dies and, means for elevating the elevating plates for moving the lower dies upwardly in the first phase of movement and then moving the carrier elements and causing the lower die elements and the plastic blank to move as a unit against the upper dies thereby bending the side portions of the blank upwardly against the inclined sides of the upper dies, the registering rounded edges of the upper dies and the grooves of the lower dies forming ridges along the lines of fold.

39. In a box making machine of the type adapted to make rectangular boxes by crimping and folding rectangular sheet plastic blanks wherein the boxes include side walls and sealing flap at each corner; a forming block of rectangular shape corresponding to that of the box, means for moving the box to position embracing said block, holding elements disposed for movement against said side walls for urging them against said block, solvent applying elements associated with certain of said holding elements adapted to engage the end margins of the side walls adjacent said flaps, means for retracting said solvent applying elements prior to retraction of said holding elements, flap folding elements on the other of said holding elements adapted to engage said flaps against the solvent coated margins of the side walls, said flap folding elements consisting of rotatably mounted elements mounted for movement around the corners of the box in a direction parallel with the bot-

tom of the box, and means for displacing said boxes from said block.

40. In a box making machine of the type adapted to make rectangular boxes by crimping and folding rectangular sheet plastic blanks; crimping means for forming the four side walls of the blank, said crimping means forming sealing flaps along the end edges of the side walls there being one flap at each corner of the box, a forming block of rectangular shape corresponding to that of the box, means for moving said box to position embracing said block, holding elements disposed for movement against said side walls for urging them against said block, solvent applying elements associated with certain of said holding elements adapted to engage the end margins of the side walls adjacent said flaps, means for retracting said solvent applying elements prior to retraction of said holding elements, flap folding elements adapted to engage said flaps against the solvent coated margins of said side walls and, means for displacing said boxes from said block.

41. In a box making machine of the type adapted to make rectangular boxes by crimping and folding rectangular sheet plastic blanks, said boxes including four side walls and sealing flaps at each corner; a forming block of rectangular shape corresponding to that of the box, means for moving said box to position embracing said block, solvent applying elements adapted to engage the end margins of the side walls adjacent said flaps, means for operating said solvent applying elements, flap folding elements adapted to engage said flaps against the solvent coated margins of the side walls, said flap folding elements consisting of rotatably mounted elements mounted for movement around the corners of the box in a direction parallel with the bottom of the box, and means for displacing said boxes from said block.

42. In a box making machine of the type adapted to make rectangular boxes by crimping and folding rectangular sheet plastic blanks; conveyor means for transporting said blanks at spaced points thereon, die means adjacent the conveyor means for forming the four side walls of the blank, said die means forming sealing flaps along the end edges of opposite side walls there being one flap at each corner of the box, a forming block of rectangular shape corresponding to that of the interior of the box, means for moving the box to position embracing said block, holding elements disposed for movement against said side walls for holding them against said block, solvent applying elements associated with certain of said holding elements adapted to engage the end margins of the side walls adjacent said flaps, means for retracting said solvent applying elements prior to retraction of said holding elements, flap folding elements on the other of said holding elements adapted to engage said flaps against the solvent coated margins of the side walls, said flap folding elements consisting of rotatably mounted elements mounted for movement around the corners of the box in a direction parallel with the bottom of the box, and means for displacing said boxes from said block.

43. In a box making machine of the type adapted to make rectangular boxes by crimping and folding rectangular sheet plastic blanks, said boxes including side walls and there being a flap at each corner of the boxes; a forming block of rectangular shape corresponding to that of the box, means for moving said box to position em-

bracing said block, solvent applying elements adapted to engage the end margins of the side walls adjacent said flaps, means for actuating said solvent applying elements and, flap folding elements adapted to engage said flaps against the solvent coated margins of the side walls.

44. A box making machine for making rectangular boxes by crimping and folding rectangular sheet plastic blanks, comprising, a continuous conveyor, means for driving said conveyor intermittently, vertically movable carrier elements mounted on said conveyor at spaced points thereon, said intermittent motions being equal in length to the spaces between said carrier elements, delivery means adjacent the conveyor for attachment of a blank to a carrier element each time the conveyor pauses, dies for trimming the corners from said blanks at the next station, wall forming dies at the next station for crimping and bending said blanks to set up the four walls, means for sealing the corners of the boxes at the last station, the several stations being spaced from one another above the conveyor at points corresponding to the position of the carrier elements when the conveyor pauses, and means for elevating the carrier elements from the conveyor into operating position with respect to the stations.

45. A box making machine for making rectangular boxes by crimping and folding rectangular sheet plastic blanks, comprising, a continuous conveyor, means for driving said conveyor intermittently, carrier elements detachably mounted on said conveyor at spaced points, said intermittent motions being equal in length to the spaces between said carrier elements, devices for detaching and translating said carrier elements independently of said conveyor at five stations along the conveyor, said stations being located adjacent successive carrier elements as the conveyor pauses, delivery means adjacent the first station for attachment of said blanks to the carrier elements at said first station, dies for trimming the corners from said blanks at the second station, wall forming dies at the third station for crimping the blank and partly setting up opposite walls, wall forming dies at the fourth station for forming the other two side walls, and means for sealing the corners of the boxes at the fifth station, said devices for detaching and translating said carrier elements relative to said conveyor being effective for moving the blanks to the mechanisms at the respective stations.

46. A box making machine for making rectangular boxes by crimping and folding rectangular sheet plastic blanks, comprising, a conveyor chain of endless loop form, sprockets supporting the respective ends of said chain, means for driving one of said sprockets intermittently, carrier elements detachably mounted on said chain at spaced points, said intermittent motions being equal in length to the spaces between said carrier elements, said carrier elements including sucker elements on their extended faces, devices for detaching and translating said carrier elements relative to said chain at five stations along one run of said chain, said stations being located adjacent successive carrier elements as the chain pauses, delivery means adjacent the first station for attachment of said blanks to the suckers of said carrier elements, dies for trimming the corners from said blanks at the second station, wall forming dies at the third station for crimping the blank and partly setting up opposite walls, wall forming dies at the fourth station for

forming the other two side walls, and means for sealing the corners of the boxes at the fifth station, said devices for detaching and translating said carrier elements relative to said chain being effective for moving the blanks to the mechanisms at the respective stations.

47. In a box making machine for making rectangular boxes by crimping and folding rectangular sheet plastic blanks; a mechanism for completing the box after the bottom, the four side walls and the sealing flaps at each corner have been formed, comprising, a central forming block of rectangular form, means for causing the partly completed box to be nested on said forming block, yieldable slides operating toward each side of the forming block, means for causing the slides at the opposite sides of the block to move inwardly for engaging the side walls adjacent thereto and clamping the same against the block, means for causing the slides adjacent the other walls to move said latter walls into position against the forming block and corner engaging devices mounted on said adjacent slides for securing the sealing flaps against the adjacent margins at each corner of the box, the said yieldable slides being constructed and arranged to yield while engaged against the latter walls to bring the corner engaging devices into engagement with the sealing flaps by continued inward movement of the slides with the walls clamped in sealing position.

48. In a box making machine for making rectangular boxes by crimping and folding rectangular sheet plastic blanks; a mechanism for completing the box after the bottom, the four side walls and the sealing flaps at each corner have been formed, comprising, a central forming block of rectangular form, means for causing the partly completed box to be nested on said forming block, yieldable slides operating toward each side of the forming block, means for causing the slides at the opposite sides of the block to move inwardly for engaging the side walls adjacent thereto and clamping the same against the block, solvent applying members yieldably mounted on the slides for applying solvent along the vertical margins of said last named side walls when the said walls are engaged against the block, means for causing the slides adjacent the other walls to move said latter walls into position against the forming block, and corner engaging devices on said last named slides for pressing the sealing flaps against those edge margins which have the solvent applied thereto, the sides which carry the said corner engaging devices being constructed and arranged to retract the solvent applying members from the said edge margins prior to pressing the sealing flaps against the edge margins.

49. In a box making machine for making rectangular boxes by crimping and folding rectangular sheet plastic blanks; a mechanism for completing the box after the bottom, the four side walls and the sealing flaps at each corner have been formed, comprising, a central forming block of rectangular form, means for causing the partly completed box to be nested on said forming block, slides operating toward each side of the forming block, said forming block including depressible fingers therein pivoted at their lower ends and normally supported in positions inclined with respect to the block for holding those side walls, which carry the sealing flaps at their ends, away from the block, means for causing the slides at the other sides of the block to move inwardly for engaging the side walls adjacent thereto and

clamping the same against the block, solvent applying members for applying solvent along the vertical margins of said last named side walls, means for causing the slides adjacent the other walls to move said latter walls into position against the forming block, and corner engaging devices on said last named slides for pressing the sealing flaps against those edge margins which have the solvent applied thereto, the slides which carry the said corner engaging devices being constructed and arranged to retract the solvent applying members from the said edge margins prior to pressing the sealing flaps against the edge margins.

50. In a box making machine for making rectangular boxes by crimping and folding rectangular sheet plastic blanks; a mechanism for completing the box after the bottom, the four side walls and the sealing flaps at each corner have been formed, comprising, a central forming block of rectangular form, means for causing the partly completed box to be nested on said forming block, slides operating toward each side of the forming block, means for causing the slides at the opposite sides of the block to move inwardly for engaging the side walls adjacent thereto and clamping the same against the block, means for causing the slides adjacent the other walls to move said latter walls into position against the forming block, devices for securing the sealing flaps against the adjacent margins at each corner of the box, plungers in said forming block having their lower ends engaged against the bottom of said box, and means for supplying air to operate said plungers to discharge the completed box from said forming block.

51. A box making machine for making rectangular boxes by crimping and folding rectangular sheet plastic blanks, comprising, a forming block, means for delivering a box to nested position on said forming block with the side walls thereof set up but not connected at the corners, means for completing said box about said forming block by joining the corners thereof, plungers disposed in the forming block and mounted for movement against the bottom of the box, means for delivering compressed air to the tops of said plungers for discharging the completed box from the block, and the bores of the plungers providing sufficient clearance for permitting the escape of air to the bottom of the box for breaking any vacuum which may exist between the box and said forming block.

52. A box making machine for making rectangular boxes by crimping and folding rectangular sheet plastic blanks, comprising, a forming block, means for delivering a box to nested position on said forming block with the side walls thereof set up but not connected at the corners, means for completing said box about said forming block by joining the corners thereof, means, operated by compressed air, disposed in the forming block for applying discharge pressure against the bottom of the box for discharging the completed box from the block and for breaking any vacuum which may exist between the box and said forming block, means for carrying said box downwardly away from the block after it is loosened therefrom, and conveyor means for picking up said latter means and transporting the box to a discharge chute.

53. A box making machine for making rectangular boxes by crimping and folding rectangular sheet plastic blanks, comprising, a forming block, means for delivering a box to nested position

on said forming block with the side walls thereof set up but not connected at the corners, means for completing said box about said forming block by joining the corners thereof, plungers disposed in the forming block and mounted for movement against the bottom of the box, means for delivering compressed air to the tops of said plungers for discharging the completed box from the block, the bores of the plungers providing sufficient clearance for permitting the escape of air to the bottom of the box for breaking any vacuum which may exist between the box and said forming block, means for carrying said box downwardly away from the block after it is loosened therefrom, conveyor means for picking up said latter means and transporting the box in a direction parallel with its bottom, and a discharge chute having a slot therein, said carrier means adapted to traverse said slot and to move angularly away from the bottom of the chute with the bottom of the box engaged on the chute whereby the box is stripped from the carrier means and discharged through the chute.

54. A box making machine for making rectangular boxes by crimping and folding rectangular sheet plastic blanks, comprising a forming block, means for delivering a box to nested position on said forming block with the side walls thereof set up but not connected at the corners, means for completing said box about said forming block by joining the corners thereof, means for discharging the completed box from the block, means for carrying said box downwardly away from the block after it is loosened therefrom, conveyor means for picking up said latter means and transporting the box in a direction parallel with its bottom, and a discharge chute having a slot therein, said carrier means adapted to traverse said slot and to move angularly away from the bottom of the chute with the bottom of the box engaged on the chute whereby the box is stripped from the carrier means and discharged through the chute.

55. In a box making machine of the type forming boxes by crimping and folding sheet plastic blanks; an elongated frame, a power driven shaft supported in said frame lengthwise thereof, a conveyor chain translatable mounted in said frame above said shaft, carrier elements detachably mounted on said chain at spaced points, said carrier elements constructed and arranged so as to grip said plastic blanks and translate them through the machine, a series of cams on said shaft, an elevating means operated by each cam, said elevating means being slideable in said frame at right angles to said chain and disposed so as to engage and move the respective carrier elements away from the conveyor chain, means for driving said chain intermittently causing the carrier elements to pause for the movements of said elevating means, means for delivering said blanks to said carrier elements, and mechanisms adjacent each elevating means for operating on said blanks to form the boxes.

56. In a box making machine of the type forming boxes by crimping and folding sheet plastic blanks; an elongated frame, a conveyor translatable mounted in said frame, carrier elements detachably mounted on said conveyor at spaced points, said carrier elements including suction cups for gripping the undersides of said plastic blanks and translating them through the machine in a horizontal plane free of any other contact with the machine in their translation, elevating means, said elevating means being slide-

able in said frame at right angles to said conveyor and disposed so as to engage and move the respective carrier elements away from the conveyor, means for driving said conveyor intermittently causing the carrier elements to pause for the movements of said elevating means, means for delivering said blanks to said carrier elements, and mechanisms adjacent each elevating means for operating on said blanks to form the boxes.

57. In a box making machine of the type forming boxes by crimping and folding sheet plastic blanks; a frame, a conveyor chain translatable mounted in said frame, carrier elements detachably mounted on said chain at spaced points, said carrier elements gripping said plastic blanks and translating them through the machine, elevating means slideable in said frame at right angles to said chain and disposed so as to engage and move the respective carrier elements away from the conveyor chain, means for driving said chain intermittently causing the carrier elements to pause for the movements of said elevating means, means for delivering said blanks to said carrier elements, and mechanisms adjacent each elevating means for operating on said blanks to form the boxes.

58. In a box making machine of the type forming boxes by crimping and folding sheet thermoplastic blanks; means for transporting said blanks through the machine at spaced intervals, trimming dies adapted to cut out the corners of the blanks, said trimming dies formed to notch out substantially rectangular portions at the corners of the blank and including additional notching portions notching out the inner corners of the rectangular portions, side wall forming dies adapted to engage the notched out blanks subsequent to the notching thereof, including heated die members adapted to crimp the plastic blanks along lines disposed across the inner corners of the additionally notched-out corners and parallel with the side edges of the blanks, the said die members being constructed and arranged to plasticize the thermoplastic blank along said lines and simultaneously to partially erect the side walls along said lines and to partially erect the portions of the blank beyond the additionally notched-out portions to form sealing flaps.

59. In a box making machine of the type forming boxes by crimping and folding sheet plastic blanks; means for transporting said blanks through the machine at spaced intervals, trimming dies adapted to cut out the corners of the blanks, said trimming dies formed to notch out substantially rectangular portions at the corners of the blank, heated side wall forming dies adapted to crimp the plastic blanks along lines parallel with the side edges of the blanks, the said forming dies being constructed and arranged to plasticize the blank along said lines and simultaneously to partially erect the side walls delineated by said lines.

60. In a box making machine of the type forming boxes by crimping and folding sheet plastic blanks; a forming block, means for nesting each plastic blank on said forming block after the plastic blank has had the respective side walls formed thereon but unattached at the corners, opposite side walls of the blank having sealing flaps along their corner edges, means cooperating with the forming block for turning said flaps and adhesively attaching them to the adjacent margins of the other side walls, and plungers operating by air pressure for mechanically discharging the completed boxes from said block and the said

plungers being constructed and arranged to supply air to the interior of the boxes to break any suction which might resist discharge.

61. In a box making machine of the type forming boxes by crimping and folding sheet plastic blanks; a frame, a conveyor mechanism mounted in said frame, said conveyor mechanism consisting of an endless loop of chain, sprockets supporting said loop at its respective ends, means for intermittently driving said chain, vertically movable carrier elements mounted in the chain at spaced points for rotation therein, sucker elements on the carrier elements for supporting the plastic blanks by gripping attachment to the undersides thereof, means intermediate the positions of pause of the chain for rotating the carrier elements for swinging the plastic blanks in their own planes, sets of wall forming dies including crimping means for crimping the blanks along lines which are parallel and aligned before and after said rotation of the blanks and means for elevating the carrier elements vertically into operating position with respect to the wall forming dies.

VINCENT D. HERY. 25
